[57] ABSTRACT

An automated offset lithographic duplicating machine permits to automatically mount a master or lithographic plate on a master cylinder, to apply ink repellent etching solution to the mounted master or lithographic plate in a time predetermined by the operator, and to perform a number of sequential duplicating steps of a duplicating cycle. The washing of a blanket cylinder, constituting the final step of the duplicating cycle of a lithographic plate, is performed in a time predetermined by the operator before the cylinder automatically stops. The number of copies to be duplicated for each lithographic plate is indicated by an indicator after marks on the lithographic plate, for indicating the number of copies to be duplicated, are read by a device provided in the machine. When the number of copies indicated by the indicator has been duplicated, washing of the blanket cylinder is automatically initiated.

DUPLICATOR MASTER FEED USING DECIMAL CODE TO SET COPY COUNT

CROSS-REFERENCE

This application is a continuation-in-part of our pending application Ser. No. 882,648, filed Dec. 5, 1969, now abandoned.

BACKGROUND OF THE INVENTION

Operation of an offset lithographic duplicating machine entails many operation steps. The main steps include (1) an ink kneading step in which ink supplied from an ink fountain is mixed with water and kneaded, (2) a lithographic plate mounting step in which a master or lithographic plate is mounted on a master cylinder, (3) an etching step in which an ink repellent etching solution is applied to the lithographic plate mounted on the master cylinder, and (4) an ink applying step in which ink is applied to the surface of the lithographic plate coated with an etching solution.

After the aforementioned steps are completed, feeding of copy sheets is initiated to start duplication. After a predetermined number of copies have been duplicated, the lithographic plate is removed from the master cylinder and the peripheral surface of the offset or blanket cylinder is washed and cleaned.

The operation steps of the offset lithographic duplicator, which begin with the kneading of ink and end with the washing of the blanket cylinder, have hitherto been performed sequentially under manual supervision. In the most up-to-date offset lithographic duplicator of the small type, it is possible to control all the steps of operation of the machine by rotating a single operation lever. However, even such a duplicator must rely on manual labor in transferring from one operation step to another.

SUMMARY OF THE INVENTION

This invention relates to offset lithographic duplicating machines comprising a master cylinder on which a lithographic plate is mounted, an offset or blanket cylinder for transferring to copy sheets an inked image transferred thereto from the lithographic plate on the master cylinder, and an impression cylinder for pressing copy sheets against the blanket cylinder.

In the offset duplicating machine according to this invention, the kneading of ink is initiated upon closing a main switch. Since this step takes a substantial time interval to perform, the operator manually manipulates the machine to set time intervals for etching, inking, and washing of the blanket cylinder, respectively, as well as stacks a number of copy sheets to be duplicated on a copy sheet feed tray, while ink is kneaded. Setting of time intervals is effected by manipulating respective time adjusting knobs disposed on the outer side of the duplicator.

After the time interval for the ink kneading operation has elapsed, a start button is depressed. A lithographic plate placed on a plate feed tray beforehand is fed by plate feed means and automatically mounted on the master cylinder. At the same time, an etching operation is initiated to apply an ink repellent etching solution to the lithographic plate mounted onto the master cylinder. The time interval for applying the etching solution is set beforehand by the operator as aforementioned. Affixed to the lithographic plate is a plurality of sets of

marks indicating the number of copies to be duplicated, which indication is read and stored in a device mounted on the duplicator while the lithographic plate mounted on the master cylinder makes one complete revolution.

After the time interval set for the etching operation has elapsed, etching is terminated and an ink applying operation is initiated to apply the kneaded ink to the surface of the lithographic plate mounted on the master cylinder. After a predetermined time interval has elapsed following initiation of ink application, feeding of copy sheets is initiated so that duplication of the lithographic plate can be started.

Each time one of the copy sheets successively fed is printed, a counter device is actuated to count the number of copies printed. A command to terminate the feeding of copy sheets is issued when the number of copies printed has reached the number stored in the register, as aforementioned, in the machine, whereby feeding of copy sheets and ink application are terminated. On the other hand, the lithographic plate on the master cylinder is automatically removed and ejected into a receiving tray. Simultaneously as the lithographic plate is removed from the master cylinder, an operation for the wasing and cleaning of the blanket cylinder is commenced. The time interval for this wasing and cleaning step is set previously as aforementioned.

When the main switch is closed as aforementioned, the machine is operating at a relatively low speed. However, the machine begins to operate at high speeds after completion of etching following the depression of a start button, returning to a slow speed operation upon completion of a predetermined duplicating cycle.

It is to be understood that, if a predetermined number of copy sheets is piled in a stack on the copy sheet feed tray and the machine is set to continuous low speed operation, the next following lithographic plate will automatically be mounted on the master cylinder upon completion of the printing of a predetermined number of copies and the wasing and cleaning of the blanket cylinder, so that duplication of a number of lithographic plates can be effected continuously without shutting off the machine.

In the offset lithographic duplicating machine according to this invention, no manual supervision of the machine is required after the start button is depressed, with all the operations necessary for completing a duplication cycle and preparing for the next duplication cycle being performed automatically.

Accordingly, a principal object of this invention is to provide an automated duplicating machine of the offset lithographic type which eliminates manual manipulation of the machine including actuation of operating levers required for operation of conventional offset lithographic duplicating machines.

Another object of the invention is to provide a device for automatically bringing an ink kneading roller assembly into and out of engagement with the master cylinder for the automated offset lithographic machine described and which requires no manual operation.

Another object of the invention is to provide an automatic etching device for the automated offset duplicating machine, which requires no manual operation.

Another object of the invention is to provide a device for automatically issuing a command for starting feeding of a lithographic plate or master and etching of the

same for the automated offset lithographic duplicating machine, which requires no manual operation.

Another object of the invention is to provide a device for automatically moving up and down master feed rollers for the automated offset lithographic duplicating machine, requiring no manual operation, which device permits the rollers for automatically feeding a master to the machine to come into contact with the master only when the feed rollers operate properly, thereby minimizing damage to the master.

Still another object of the invention is to provide a device for opening and closing pawls for the automated offset lithographic duplicating machine, requiring no manual operation, which device is adapted to automatically grip a master cylinder when the master has been automatically fed to the machine.

Still, another object of the invention is to provide a device for detecting if a copy sheet is properly gripped by pawls on the impression cylinder for the automated offset lithographic duplicating machine, which requires no manual operation.

A further object of the invention is to provide a sheet copy counting device and a jogger device for the automated offset lithographic duplicating machine, requiring no manual operation, which counting device is adapted to count the number of copy sheets fed to the machine by the copy sheet feed mechanism and which jogger device is coupled to movable side plates mounted on the printed copy receiving tray for jerking a lateral side edge and a rear edge of a stack of duplicated copies only when a fresh copy is duplicated.

A further object of the invention is to provide a device for automatically removing a master from the master cylinder on which it is mounted for the automated offset lithographic duplicating machine, which requires no manual operation.

A still further object of the invention is to provide a blanket cylinder washing device for the automated offset lithographic duplicating machine, requiring no manual operation, which device is adapted to automatically wash and clean the blanket cylinder at the end of a duplication cycle.

A still further object of the invention is to provide a device for reading the number of printed copies for the automated offset lithographic duplicating machine, requiring no manual operation, which device reads a predetermined number of copies to be duplicated which are printed as timing marks on a marginal portion of a master and stores the read-out information so as to automatically shut off the copy sheet feed device after the predetermined number of copies have been duplicated.

Additional objects as well as features and advantages of this invention will become evident from consideration of the description set forth hereinafter when considered in conjunction with the accompanying drawings.

BRIEF DESCRIPTION OF THE DRAWING

In the Drawings:

FIG. 1 is a left side view of an offset lithographic duplicating machine embodying the present invention;

FIG. 2 is a right side view of the machine of FIG. 1;

FIG. 3 is a side view of a mechanism for bringing an ink kneading roller assembly into and out of engagement with the master cylinder;

FIG. 4 is a side view showing the manner of operation of the mechanism of FIG. 3;

FIG. 5 is a fragmentary enlarged side view of FIG. 3;

FIG. 6 is a fragmentary side view showing the lower half of FIG. 3;

FIG. 7 is a side view of a roller assembly supporting device adapted to be actuated by the mechanism shown in FIG. 3;

FIG. 8 to 10 are side views showing the manner of operation of the roller assembly of FIG. 7;

FIG. 11 is a side view showing a plate feed device for feeding a lithographic plate or master to the machine;

FIG. 12 is a side view of the master feed device showing its manner of operation upon issuing of a command to feed a master;

FIG. 13 is a sectional view along the line W-W of FIG. 11;

FIG. 14 is a perspective view showing certain parts of the plate feed device;

FIG. 15 is a side view of FIG. 14;

FIG. 16 is a fragmentary side view of FIG. 14;

FIG. 17 is a side view showing the manner in which a lithographic plate is supplied;

FIG. 18 is a side view showing the manner in which a supplied lithographic plate is caught by gripping pawls on the master cylinder;

FIG. 19 is a side view of a stop means adapted to be rendered operative when the lithographic plate fails to be mounted on the master cylinder;

FIG. 20 is a perspective view of master gripping pawls and master detection pawls mounted on the master cylinder;

FIG. 21 is an enlarged view of a master gripping portion on the master cylinder;

FIG. 22 is a side view of an ink repellent etching liquid applicator;

FIG. 23 is a fragmentary perspective view of the etching liquid applicator;

FIG. 24 is a perspective view of a device for bringing master feed rollers into and out of engagement with each other;

FIGS. 25 to 28 are side views showing the manner of operation of a device for bringing the master supply roller into and out of engagement with the uppermost layer of a pile of masters which operates in association with the etching liquid applicator;

FIG. 29 is a plan view of a lithographic plate or master bearing marks indicating the number of copies to be printed for the offset lithographic duplicator according to this invention;

FIG. 30 is a schematic view of a mark read-out device for optically reading the marks on the lithographic plate;

FIG. 31 is a view in explanation of the relation between the marks on the lithographic plate and a light receiving element;

FIG. 32 is a block diagram of a duplication control device for automatically setting the number of copies to be duplicated in accordance with the marks printed on the lithographic plate and automatically shutting off a sheet feed device upon completion of printing of the predetermined number of copies;

FIG. 33 is a plan view of the impression cylinder;

FIG. 34 is an enlarged sectional view along the line X-X of FIG. 33;

FIG. 35 is a side view showing a device for bringing the impression cylinder into and out of engagement with the blanket cylinder;

FIGS. 36 and 37 are side views showing the manner of operation of the device shown in FIG. 35;

FIG. 38 is a fragmentary side view of FIG. 36;

FIG. 39 is a perspective view of release means connected to the device of FIG. 35;

FIG. 40 is a side view of a copy sheet gripping device;

FIG. 41 is a side view showing the manner in which the gripping pawls are actuated;

FIG. 42 is a side view of a copy sheet push-out device;

FIG. 43 is a plan view of a printed copy receiving tray;

FIG. 44 is a side view of FIG. 43;

FIG. 45 is a bottom plan view of FIG. 43;

FIG. 46 is a perspective view of a mechanism for moving a side plate mounted on the printed copy receiving tray;

FIG. 47 is a fragmentary side view of FIG. 46;

FIG. 48 is a sectional view along the line Y—Y of FIG. 45;

FIG. 49 is a sectional view along the line Z—Z of FIG. 45;

FIG. 50 is a central transverse sectional view of FIG. 45;

FIG. 51 is a side view of a master removing and ejecting device;

FIG. 52 is a side view showing a lithographic plate immediately before its front end clears the master cylinder;

FIG. 53 is a fragmentary side view showing the manner in which the front end of a lithographic plate is guided by guide pawls;

FIGS. 54 and 55 are side views showing the essential portions of a device for opening the master grip pawls;

FIG. 56 is a sectional view of a blanket cylinder washing and cleaning device;

FIG. 57 is a perspective view of the device of FIG. 56;

FIG. 58 is a circuit diagram showing one example of the circuitry for a portion of the duplication control device shown in FIG. 32;

FIG. 59 is a circuit diagram showing one example of the circuitry for other portions of the duplication control device shown in FIG. 32; and

FIG. 60A to FIG. 60C are circuit diagrams showing portions of the electric circuitry for the offset duplicating machine according to this invention.

DESCRIPTION OF THE PREFERRED EMBODIMENT

In FIG. 1, a panel 2 is fixed to a left side plate of the machine 1 and spaced apart a certain distance therefrom. Mounted on panel 2 are an etching time control knob 3, an ink applying time control knob 4, and washing time control knob 5. Another panel 6 disposed in end to end relation with the panel 2 mounts thereon a start button 7, a temporary stop button 8, button 9 for switching between automatic and manual setting of the number of copies to be printed, button 10 for switching the master feed operation, and button 11 for switching between the modes of indication of the number of printed copies.

Button 9 for switching between automatic and manual setting of the number of copies to be printed is used for selecting whether the number of copies to be duplicated is automatically set by means of the marks on a master or manually set. Button 10, for switching the master feed operation, is adapted for use in selecting

whether or not the next following master should be fed to the machine upon completion of duplication of a predetermined number of copies for one master. The button 11, for switching between the modes of indication of the number of printed copies, is used for selecting whether the number of printed sheets indicated represents a total of printed copies for each master or a grand total of printed copies for a series of masters.

Disposed to the right of panel 6 are a printed copy number indicator 12, predetermined printed copy number setter 13 for manually setting the number of copies to be printed beforehand, and indicator tube 14 for indicating the number of copies to be printed in accordance with the marks printed on a master.

15 There are provided a master cylinder 15, offset or blanket cylinder 16 and impression cylinder 17 which are coupled to one another through gears of the same diameter provided with the same number of teeth. These cylinders are adapted to rotate in opposite directions, as indicated by the respective arrows in FIG. 1 when a main switch of the machine is closed.

A variable number of masters or lithographic plates 19 is disposed on a master feed tray 18. Upon depression of the start button 7, the uppermost master sheet is fed to the machine and mounted on the master cylinder 15. A stack of copy sheets 20 is supported on a sheet feed tray 21. Each master or lithographic plate 19 is removed from the master cylinder 15 and ejected into a master receiving tray 22 upon completion of duplication of the predetermined number of copies. The printed copies are discharged into a printed copy receiving tray 23. An oscillating side plate 24 is removed in vibratory motion for pushing, with a jerk, lateral edges of printed copies on the printed copy receiving tray in association with the duplicating operation.

Upon turning on of the main switch of the machine, an ink kneading operation is initiated. A mechanism for controlling the operation of an ink kneading roller assembly is mounted on a right side plate 25 of the machine shown in FIG. 2. If the main switch (not shown) is closed, then a solenoid 26 shown in FIG. 3 is actuated to move a bar, plunger or armature 27 thereof in the direction of the arrow, which bar 27 moves a pin 29, fixed to the upper end of an actuating member 28, against the biasing force of a spring 30 acting on actuating member 28, so that the actuation member 28 moves in a counterclockwise direction about a shaft 31. A first locking member 32 and a connecting member 33 are rotatably supported by shaft 31, with a spring 34 being connected between the actuating member 28 and connecting member 33 and a compression spring 35 being connected between the connecting member 33 and the distal end of first locking member 32. Mounted at the free end of the connecting member 33 is a roller 36 which is loosely received in a groove 37a formed by bent opposite edges of a first connecting rod 37. Rod 37 is pivotally connected at one end, through a pin 40, to the upper end of a follower arm 39 of a cam 38 fixed with the blanket cylinder 16. The follower arm 39 is pivoted on a shaft 41 supported by the right side plate of the machine. A roller of the follower arm 39 is urged to press against the cam 38 by the biasing force of a spring 42 acting on the follower arm 39. Formed at the other end of the first connecting rod 37 is an L-shaped slot 43 in which is loosely received a pin 47a fixed to an oscillating cam 47 which is secured to a shaft 46 to which a short arm 44 is fixed. Cam 47 moves a follower

arm 48 pivoted on a shaft 49 fixed to the right side plate of the machine. A roller 50 mounted on a pin connected to the follower arm 48 is urged to press against a side edge of the oscillating cam 47 by the biasing force of a spring 51 acting on the follower arm 48. Attached to the follower arm 48 is a pin 52 which is loosely received in an L-shaped slot 54 formed at one end of a second connecting rod 53 which is pivotally connected at the other end through a pin 57 to the lower end of a lever 56 pivotally supported by a shaft 55 fixed to the right side wall of the machine. A follower 58 of the cam 38 is loosely mounted on shaft 55, and a pin 60, fixed to the upper end of lever 56 to extend inwardly of the duplicator, is urged by a spring 61 to press against a right lateral edge of follower 58 so as to cause a roller 59 to press against the cam 38.

Disposed in the vicinity of the second connecting rod 53 are a second locking member 62, actuating member 63 and connecting member 64 which are mounted on a shaft 65 for oscillating motion. A roller 66 mounted on the forward end of connecting member 64, extending obliquely upwardly, is loosely received in a groove formed in the second connecting rod 63 formed by bent edges thereof. The upper end of actuating member 63 is connected to a movable bar or plunger 68, of a solenoid 67, by a connecting link 69. The actuating member 63 and connecting member 64 are connected to each other by a spring 70, and the connecting member 64 and second locking member 62 are connected to each other by a spring 71.

A pin 73, attached to an arm 72 disposed below the second connecting rod 53, is loosely received in a slot 75 formed in the lower end of a connecting rod 74 connected to the forward end of the short arm 44 through a pin or pivot 45. Fixed to the forward end of an arm 77, attached to a shaft 76 to which arm 72 is attached, is a pin 78 which faces inwardly and extends loosely through an opening 79 formed in the right side plate to project inwardly of the side plate of the machine.

The inner end of the shaft 46 to which the oscillating cam 47 is fixed and the inner end of the shaft 49 to which the follower arm 48 is fixed project inwardly of the side plate of the machine, with cams 80 and 81 being fixed to the respective inner ends as shown in FIG. 7. A roller 84 mounted on an arm 83, which mounts a roller 82 at its free end, presses against the cam 80, and rollers 87 and 88, mounted on the distal ends of respective arms 85 and 86, press against the cam 81. The arm 83, which is pivotally mounted on a shaft 89 inwardly of the side plate of the machine, is urged upwardly by the biasing force of a spring (not shown). Thus, the roller 82 is normally disposed in a position in which it is spaced apart from two rollers 90 and 91. The arms 85 and 86 are pivotally mounted on a shaft 93 supporting the roller 91, with the arm 85 being urged to move in a counterclockwise direction and the arm 86 being urged to move in a clockwise direction by respective springs (not shown). The rollers 87 and 88, mounted on the distal ends of the respective arms 85 and 86, are pushed upwardly by a major diameter portion of the cam 81, so that ink form rollers 94 and 95, mounted on the respective arms 85 and 86, are kept from pressing against the master cylinder. A bearing 96 of the ink form roller 94 is urged away from the shaft 93 by a cam 97 fixed to the inner side of the side plate of the machine, and a bearing 98 of the ink form roller 95 is urged away from the shaft 93 by a cam 99

similar to cam 97. Thus, the ink form rollers 94 and 96 are both disposed away from the roller 91.

A roller 100 disposed below the roller 91 is immersed in its lower marginal portion in the water contained in a water fountain (not shown), with a water ductor roller 101 pressing against roller 100. A bar 102, for supporting the water ductor roller 101, is pivotally supported by a shaft 103 of the fountain roller 100. The supporting bar 102 is urged by the biasing force of a spring (not shown) to move in a clockwise direction. An arm 102a extending from the supporting bar 102 abuts against the pin 78, thereby preventing the water ductor roller 101 from pressing against the roller 91.

The operation of the aforementioned device for bringing an ink applying roller assembly into and out of engagement with the master roller will now be explained. Upon actuation of the solenoid 26 (FIG. 3), the actuating member 28 pivots counterclockwise about the shaft 31. This causes the connecting member 33 to be pulled by the spring 34 to pivot counterclockwise about the shaft 31, so that the roller 36, mounted on the connecting member 33 causes the first connecting rod 37 to pivot counterclockwise about the shaft 40. As a result, a hooked portion 43a at the left end of the L-shaped slot 43 engages the pin 47a and the first locking member 32 is pulled by the spring 35 to pivot counterclockwise about the shaft 31, so that a bent portion 32a, at the forward end of the first locking member 32, is caused to press against the upper lateral edge of the first connecting rod 37. At this time, a protuberance 38a on the periphery of the cam 38, substantially integral with the blanket cylinder 16, pushes the follower arm 39 outwardly against the biasing force of the spring 42 as shown in FIG. 4. This causes the first connecting rod 37 to move from the position shown in FIG. 3 to the position shown in FIG. 4, with an offset portion 37a, formed on the upper lateral edge of the first connecting rod 37, being brought into engagement with the bent portion 32a of the locking member 32. As a result, the oscillating cam 47 is moved together with the short arm 44 counterclockwise into an operative position by hooked portion 43a of the L-shaped slot 43 against the biasing force of the spring 104. The cam 47 is maintained in this operative position during a duplication cycle by the solenoid 26 which continues to operate till a predetermined duplication cycle is completed.

The first connecting rod 37 is released from engagement with the first locking member 32 when the main switch is turned off and the solenoid 26 is rendered inoperative at the termination of a duplication cycle. As soon as the solenoid 26 is rendered inoperative, the roller of the follower arm 39 rides on the protuberance 38a of the cam 38, so that cutout 37a of the first connecting rod 32 is released from pressing engagement with the bent portion 32a at the forward end of the first locking member 32. The oscillating cam 47 pushes the roller 50 outwardly, causing the follower arm 48 to pivot, with the shaft 49, in a clockwise direction against the biasing force of the spring 51. This causes the cam 81, fixed to the shaft 49, to rotate in the clockwise direction from a position shown in FIG. 7, with the result that the roller 88 is engaged in an offset portion 81a of the cam 81 and the roller 87 is engaged in an offset portion 81b of the cam 81. This results in the arms 85 and 86 pivoting slightly in counter-clockwise and clockwise directions, respectively. This causes the bearing 96 of one ink form roller 94 and the bearing 98 of the other

ink form roller 95 to slip off a small distance from the fixed cams 97 and 99, respectively, so that the ink form rollers 94 and 95 both press against the roller 91.

The bearings 96 and 98 of the respective ink form rollers 94 and 95 are urged inwardly by the biasing force of expansion springs 105 and 106, respectively. On the other hand, when the oscillating cam 47 swings counterclockwise from the position shown in FIG. 3 to the position shown in FIG. 4, the cam 80, fixed to the shaft 46 of the cam 47, rotates counterclockwise, so that the cam 80 moves the roller 84 downwardly and the arm 83 pivots counterclockwise about the shaft 89. This causes the roller 82 to press against the rollers 90 and 91 from which it is normally spaced apart. A bearing 108 of the roller 82 is normally urged downwardly by a spring 107. Also, as the upper end of the connecting rod 74 is pulled with the short arm 44 by the first connecting rod 37, the connecting rod 74 moves downwardly and the pin 73, moving with the connecting rod 74 in slaved relation, pivots about the shaft 76 in an amount corresponding to the downward movement of the connecting rod 74. This causes the arm 77, substantially integral with the arm 72, to pivot counterclockwise about the shaft 76, with the pin 78 fixed to the arm 77 being released from engagement with the arm 102a of the supporting bar 102 (See FIG. 7). This results in the supporting bar 102 pivoting in a clockwise direction about the shaft 103, thereby bringing the roller 101 into pressing engagement with the roller 91.

From the foregoing description, it will be appreciated that, as the first connecting rod 37 moves to the left from the position shown in FIG. 3 to the position shown in FIG. 4, all the rollers concerned in an ink kneading operation, which are spaced apart from one another, as shown in FIG. 8, are brought into engagement with one another, as shown in FIG. 9, so that kneading of ink can be effected. At this time, the ink form rollers 94 and 95 are spaced apart from the master cylinder.

Upon pressing of the start button following completion of the ink kneading operation, a lithographic plate or master is automatically mounted on the master cylinder and at the same time an etching operation is initiated. As aforementioned, the time interval for effecting etching is set beforehand by the operator, so that the solenoid 67 is automatically energized as soon as the etching operation is completed after the predetermined time has elapsed.

While the ink kneading operation is in progress, the follower arm 48 remains in a position shown in FIG. 4, to which it has been moved by the oscillating cam 47, with the pin 52 fixed to the arm 48 being disposed under the hooked portion 54a of the L-shaped slot 54. If the solenoid 67 (See FIG. 3) is actuated to cause the actuating member 63 to pivot in a clockwise direction about the shaft 65 at this time, then the connecting member 64 is pulled by the spring 70 to pivot about the shaft 65. As a result, the roller 66 of the connecting member 64 causes the second connecting rod 53 to pivot clockwise about the shaft 57, thereby bringing the hooked portion 54a into engagement with the pin 52. On the other hand, the second locking member 62 is pulled by the spring 71 to pivot in a clockwise direction about the shaft 65, with a bent portion 62a at its forward end being caused to press against the lower edge of the second connecting rod 53. If the roller 59 is pushed outwardly by the cam 38 and the lever 56 pivots in a clockwise direction at this time, then the second

connecting rod 53 is pulled to the left as seen in FIG. 6, with the bent portion 62a of the second locking member 62 being engaged in a cutout 53a formed in the lower edge of the second connecting rod 53.

5 The second connecting rod 53 is released from engagement with the second locking member 62 when the solenoid 67, for issuing a command to effect ink application, is rendered inoperative upon completion of a duplication cycle. As soon as the solenoid is rendered 10 inoperative, the roller 59, fixed to the follower 58, rides on the protuberance 38a of the cam 38, thereby releasing the bent portion 62a of the forward end of the second locking member 62 from engagement in the cutout 53a of the second connecting rod 53. As the second 15 connecting rod 53 is moved to the left as seen in FIG. 3, the pin 52 engaged by the hooked portion 54a is pulled by rod 53, with the result that the follower 48 pivots in a clockwise direction from the position shown in FIG. 4 to the position shown in FIG. 6. The pivotal movement of the follower 48 causes the shaft 49 fixed thereto to rotate simultaneously, thereby causing the cam 81 (See FIG. 7) fixed to the shaft 49 to rotate in a clockwise direction. This causes the rollers 88 and 87, which are received in the offset portions 81a and 81b, respectively, to be released from engagement with the respective offset portions, thereby causing the arms 85 and 86, supporting the ink form rollers 94 and 95, respectively, to pivot counterclockwise and clockwise, respectively. Thus, the ink form rollers 94 and 95 are 20 brought into engagement with the master cylinder 15 while the rollers 94 and 95 are both maintained in engagement with the roller 91, as shown in FIG. 10, so that ink can be applied to a lithographic plate mounted on the master cylinder, and which has already been 25 etched.

The second connecting rod merely moves in reciprocating motion after the etching operation is completed till the solenoid 67 is energized.

30 Before ink is applied to a lithographic plate on the master cylinder after completion of the ink kneading operation, an automatic master mounting step, printed copy number reading step and etching step must be performed. A command to feed a lithographic plate from the master feed tray and a command to start etching are given simultaneously to a solenoid 110, shown in FIG. 11, by operating a start button. As the solenoid 110, which is mounted on the left side plate 1, is energized in accordance with these commands, the operations of mounting a lithographic plate on the master cylinder, reading the number of copies to be duplicated and applying an etching solution to the lithographic plate on the master cylinder are started.

35 Mounted on the left side of the solenoid is a push bar 112 having a roller 111, which push bar is adapted to move leftwardly of the solenoid 111 as a movable, plunger, or armature 113 of the solenoid is moved to the left upon energization of the solenoid. Fixed to the left side plate 1 of the machine in positions, obliquely staggered relative to each other, are two pins 114 and 40 115 which mount a first sliding member 116 and second sliding member 117, the two sliding members being of substantially the same width and capable of moving in sliding motion a distance corresponding to the major dimension of slots 116a and 117a respectively. The second sliding member 117 is pivotally connected at one end to the free end of an arm 119 mounted on a shaft 118 and at the other end to the cen- 45 50 55 60 65

tral portion of an engaging arm 120. The engaging arm 120 is pivotally mounted on a shaft 121 supported by the side plate 1 and has a free end which is formed with an offset portion 120a which is engaged by a square pin 123 fixed to a segmental gear 122 and facing outwardly. The segmental gear 122 is pivotally mounted on a shaft 124 to be disposed inwardly of the left side plate 1, and the square pin 123 extends outwardly through an arcuate opening 125 formed in the side plate 1. The segmental gear 122 is pulled upwardly by a wire 127 secured at one end to the shoulder of the gear and connected at the other end to one end of a spring 128 of relatively high resilient force which is connected at the other end to the side plate 1. Thus, the square pin 123 presses strongly against the offset portion 120a of the engaging member 120.

Fixed to the upper end of the first sliding member 116 is a pin 129 which extends outwardly through the slot in the second sliding member 117. Connected between pin 129 and a pin 130 is a spring 131 which urges the first sliding member 116 obliquely upwardly and leftwardly in relation to the second sliding member 117. The second sliding member 117 is urged obliquely upwardly and the in relation to the side plate 1 by a spring 133 connected between the pin 115 and a pin 132. A pin 134 fixed to the inner surface of the first sliding member 116 is loosely received in a lever 136 pivotally mounted on a shaft 135 supported by the side plate. The lower edge of a rightwardly extending arm of lever 136 engages the roller 111. A locking arm 410 is pivotally mounted at its base on the pin 115 and has a projection 410b at its free end which is disposed at the end of the path of movement of the square pin 123.

The shaft 118, on which the arm 119 is mounted, is rotatably supported at opposite ends by the left and right side plates of the machine as shown in FIG. 14. Mounted internally of the right side plate at the end of shaft 118 opposite to the end at which the arm 119 is mounted is an engaging arm 137 which engages a bent portion 139a of a locking piece 139 secured to an internally toothed segmental gear 138 which is pivotally mounted on a shaft 140 secured to the inner surface of the right side plate of the machine. The segmental gear 138 is normally urged by a spring 141, of relatively high resilient force to rotate counterclockwise about the shaft 140, with counterclockwise movement being checked by locking piece 139 and locking arm 137 which engages leveling piece 139.

In meshing engagement with the segmental gear 122 is a gear 144 loosely mounted on shaft 143 supporting a master feed roller 142, which gear 144 is connected to shaft 143 by a unidirectional clutch 145 which transmits rotation in only one direction. The gear 144 is rotated by the segmental gear 122, in reciprocating motion, in both clockwise and counterclockwise direction. The clutch 145 is adapted to transmit, to the shaft 143, the rotation of gear 144 only when the gear 144 rotates in a clockwise direction and not to transmit the rotation when the gear 144 rotates counterclockwise. A relatively short arm 146, pivotally connected at its lower end to a pin 126 secured to the shoulder of the segmental gear 122, is formed at its upper end with an opening which loosely receives therein a pivot shaft 408 which is secured by a nut and screw at a suitable position in the edge of a slot 149 formed at the forward end of an arm 148 secured to a gear 147. The position at which the pivotal shaft 408 is mounted may be adjusted so

that the angle of rotation of a master supply roller 151 can be varied as desired. A shaft 150 mounting the gear 147 is supported at one end by a doubling plate disposed in side by side relation with the left side plate of the duplicator on its inner side and supports, at its other end, one end of a shaft 409 (FIG. 13) supported at its other end by a doubling plate disposed in side by side relation with the right side plate of the duplicator. A pair of oscillating plates 152, rotatably supporting the master supply roller 151 for supplying a master, are loosely mounted on shaft 409, and the master supply roller 151 is connected to the gear 147 through a gear 154, loosely mounted on a shaft 153 supporting the master feed roller, and an intermediate gear 155. As shown in FIG. 17, the master feed roller shaft 153 is connected to the gear 154 through a unidirectional clutch 156 which is adapted to transmit the rotation of the gear 154 to the shaft 153 only when the gear 154 rotates in the direction of the arrow.

In meshing engagement with the internally toothed segmental gear 138 (See FIG. 22), adapted to operate the etching device, is a gear 157 which is mounted on a tubular shaft 158 loosely fitted over a shaft 159 rotatably supported by the side plate of the duplicator. An arm 160, having a pin 160a secured to its free end, is secured to the inner end of the tubular shaft 158. A sprocket wheel 161, through which the tubular shaft 158 loosely extends, is secured to an immovable member of the duplicator, such as the side plate or doubling plate. Fixed to the shaft 159 is a supporting arm 162 which is adapted to bear against the pin 160a, arm 162 rotatably supporting, at its free end, a shaft 164 which mounts, at its outer end, a sprocket wheel 163. The fixed sprocket wheel 161 and the rotatable sprocket wheel 163 are connected to each other by an endless chain 165. Attached to the inner end of the shaft 164 is an ink repellent etching solution applicator 166 hexagonal in cross-section and having a width slightly larger than the width of the lithographic plate or master, and which is made of a material adapted to be immersed in an ink repellent etching solution. Connected to the outer end of the shaft 159 which extends outwardly of the right side plate of the duplicator is an engaging member 167 which has a bent end portion 167a adapted to be locked by a locking arm 168 (See FIG. 22) pivotally mounted on a shaft 169 on the outer surface of the right side plate. Shaft 169 mounts an arm 170 for pivotal motion, and arm 170 is connected, at its lower end, to a movable armature or plunger 172 of a solenoid 171 through a connecting link 173. A pin 174 secured to the arm 170 is connected to the locking arm 168 by a spring 175.

In FIG. 24, a roller 176, forming a pair with the master feed roller 142, is supported by a pair of oscillating members 178 and 179 supported by a shaft 177 secured at one end to the side plate of the machine, and rollers 180 and 181 are mounted on the lower ends of the oscillating members 178 and 179, respectively. Roller 180 bears against the upper edge of a relatively short arm 182 and roller 181 bears against the upper edge of an arm 183 having a greater length than arm 182. Arm 182 is firmly fixed to one end of a shaft 184 rotatably supported by the side plate of the duplicator, and arm 183 is firmly fixed to the other end of shaft 184. A follower arm 185, fixed to one end of the shaft 184, mounts, at its free end, a roller 186 which is urged by the biasing force of a spring (not shown) to press

against the periphery of a cam 187 which is fixed with the master cylinder 15. As shown in FIG. 15, another cam 188 substantially integral with the master cylinder is mounted over the cam 187. A roller 189 mounted on a shaft supported by the distal end of the segmental gear 122 presses against the cam 188. A cam 190, shown in FIGS. 14 and 16, which is fixed to one end surface of the master cylinder, is adapted to act on a roller 191 mounted on the internal segmental gear 138. In FIGS. 24 to 28, an upright bar 192 is shown as secured at its lower end to the forward end of the arm 183. A locking member 193, formed at its lower end with a hook 193a and having a resilient wire 194 secured to its base at one side of its upper portion, is mounted adjacent upright bar 192 on a shaft 195 supported by the side plate of the machine. A loop 194a formed at the free end of the resilient wire 194, surrounds a pin 196 secured to one end of the internally toothed segmental gear 138.

In FIGS. 15 to 17, an elongated oscillating cam 197 is illustrated as pivotally supported, at its base, by a shaft 198 supported by an immovable member, and as urged by the biasing force of a spring 308 to press, at its forward end portion, against a pin 200 connected to an arm 199 which is substantially integral with the segmental gear 122.

Mounted on one end surface of the master cylinder is a master gripping pawl opening and closing arm 202 which mounts, at one end, a roller 201 as shown in FIG. 18. A shaft 203, having arm 202 secured to its outer end, is rotatably supported by opposite end plates of the master cylinder 15. Master grip pawls 204 are secured to the shaft 203. The arm 202 is normally urged by the biasing force of a spring 205, mounted between the master cylinder 15 and the arm 202, to move in a clockwise direction with respect to the master cylinder. Accordingly, the master grip pawls 204 press against a flat surface 15b between a relatively large cutout 15a, formed in the master cylinder 15, and the peripheral surface of the master cylinder, as shown in FIG. 21.

Another shaft 206, disposed in parallel relation with the shaft 203, is also rotatably supported by the master cylinder 15 and has master push pawls 207 secured thereto. The outer end of shaft 206 extends out of the other end surface of the master cylinder 15 and has a bifurcated member 208 secured thereto. A roller 209, mounted on one arm of bifurcated member 208, is urged by the biasing force of a spring 211 to press against a cam 210 fixed to the inner surface of the right side plate of the duplicator. Spring 211 is connected, at one end, to the end of one arm of the bifurcated member 208 and, at the other end, to one part of the master cylinder. The forward end portions of the master push pawls 207 are bent inwardly as shown in FIGS. 20 and 21, with forward end portions 207a of the pawls being normally disposed in a recess in the flat surface 15b of the master cylinder.

If the start button is depressed after completion of the ink kneading operation, then the solenoid 110 (See FIG. 11) is actuated to move the push bar 112 leftwardly against the biasing force of a spring (not shown). The roller 111 mounted on the push bar 112 causes the lever 136 to swing counterclockwise about the shaft 135, permitting the first sliding member 116 to move downwardly and obliquely rightwardly against the biasing force of the spring 131. The first sliding member 116 is formed with a shallow cutout 116b on

one side of the lower portion. When the sliding member 116 moves as aforementioned, a bent portion 410a of the locking arm 410 is engaged in cutout 116b as shown in FIG. 12 to prevent the return movement of the sliding member 116. The aforementioned movement of the first sliding member 116 charges the spring 131, so that the second sliding member 117 is pulled by the spring 131 to move in the same direction as the first sliding member 116. However, the movement of the second sliding member is prevented by the square pin 123 strongly pressing against the offset portion 120a of the engaging arm 120. The movement of the second sliding member is prevented not only by the engagement of the square pin 123 with the engaging arm 120 but also by the engagement of the engaging arm 137 with the locking piece 139, engaging arm 137 being secured to the other end of the shaft 118 which mounts the arm 119 at one end. That is, the movement of the second sliding member 117 under the bias of the spring 131 is prevented so long as the bent portion 139a of the locking piece 139 strongly presses against the engaging arm 137.

If the master cylinder 15 rotates so that the cam 188 pushes the roller 189 outwardly as shown in FIG. 15 while the spring 131 remains charged, the segmental gear 122 moves slightly in a clockwise direction about the shaft 134 to weaken the force with which the square pin 123 engages the engaging arm 120. If further rotation of the master cylinder 15 causes the cam 190 to push the roller 191 of the internally toothed segmental gear 138 outwardly as shown in FIG. 16, the internally toothed segmental gear 138 moves slightly in a clockwise direction about the shaft 140, thereby weakening the force with which the engaging arm 137 engages the locking piece 139. Weakening of the force with which the engaging arm 137 engages the locking piece 139 takes place while the force with which the square pin 123 engages the segmental gear 122 is being weakened or the roller 189 is being pushed outwardly by the cam 188.

The restraining forces exerted on the second sliding member 117 are all removed when the force with which the locking piece 139 of the internally toothed segmental gear 138 is engaged by the engaging arm 137 is weakened following the weakening of the force with which the square pin 123 engages the engaging arm 120. Thus, the second sliding member 117 is rapidly moved downwardly and obliquely rightwardly by the biasing force of the spring 131. This causes the engaging arm 120 to swing counterclockwise about the shaft 121 as shown in dash-and-dot lines in FIG. 17 so as thereby to release the engaging arm from engagement with the square pin 123. Thereafter, when the cam 188 further rotates counterclockwise with the master cylinder so that the roller 189 is positioned against the minor diameter portion 188a of the cam 188, the segmental gear 122 is pulled upwardly by the wire 127. When the segmental gear 122 is in this position, it causes the gear 144 to rotate but the rotation of gear 144 is not transmitted to the shaft 143 by the action of clutch 145, with a result that the roller 142 remains stationary. On the other hand, the gear 147 connected to the segmental gear 122 is caused to rotate in the direction of arrow by the link 146 which turns the gear 147, so that the gear 154 is caused to rotate in the direction of arrow by the gear 147. This causes the shaft 153 to rotate in the same direction, this shaft being connected

to the gear 154 through the clutch 156, whereby a lithographic plate or master 19a is fed by the master supply roller 151 and its forward end edge is nipped by the master feed rollers 176 and 142. If the roller 189 is pushed outwardly by the cam 188 while the master 19a is in this position, the segmental gear 122 moves in a clockwise direction about the shaft 124 against the tensile force of the wire 127. The rotation of the segmental gear 122 is transmitted to the gears 144 and 147. The rotation of gear 147 is not transmitted to the master supply roller 151 due to the action of the clutch, and the rotation of gear 144 is transmitted to the master feed roller 142. Thus, the master 19a is fed to the master cylinder by the master feed rollers 142 and 176.

FIG. 18 shows the forward end edge of the master 19a about to be inserted in the grip pawls 204 after the master 19a has been moved leftwardly by the master feed rollers 142 and 176. When the segmental gear 122 turns counterclockwise as shown in FIG. 17, the pin 200 secured to the arm 199 pushes the oscillating cam 197 downwardly, causing the free end 197a of the cam 197 to be engaged in a cutout 212a formed in a locking member 212. The locking member 212 is pivotally supported by a shaft 213 connected to the inner side of the left side plate of the duplicator and normally urged by the biasing force of a spring (not shown) to swing counterclockwise. This prevents the oscillating cam 197, engaged in the cutout 212a, from being restored to its original position.

As the oscillating cam 197 is pushed downwardly, its lower side edge is positioned in the path of travel of the roller 201 of the master grip pawl opening and closing member 202. Therefore, as the roller 201 of the opening and closing member 202, rotating with the master cylinder 15 passes by the lower side of the oscillating cam 197, the roller 201 is pushed by the lower side edge of the oscillating cam 197, thereby causing the opening and closing member 202 to pivot counterclockwise. As a result, the shaft 203 mounting the opening and closing member 202 moves counterclockwise thereby opening the master grip pawls 204.

Further counterclockwise rotation of the master cylinder 15 from the position shown in FIG. 18 brings the roller 201 out of engagement with the oscillating cam 197, whereby the master grip pawls 204 are closed to hold the forward end edge of the master 19a against the master cylinder. When the master grip pawls 204 are in an open position, the master push pawls 207 remain closed. Accordingly, when the master is caught by the grip pawls 204, the forward ends 207a of the master push pawls 207 are disposed below the master 19a as shown in FIG. 20.

If the master cylinder fails to grip the master 19a and rotates without the master thereon into a position shown in FIG. 19, then the roller 209 of the bifurcated member 208 is engaged in a minor diameter portion 210a of the fixed cam 210, whereby the bifurcated member 208 is caused to swing counterclockwise. Pivotal movement of the bifurcated member 208 causes the end 208a of the other arm thereof to project outwardly to kick a pin 215 secured to the forward end of an arm 214 (See FIG. 19) and cause the forward end of bent arm 216 to oscillate an actuating member 218 of switch 217, thereby actuating the switch 217. This switch 217 provides an indication that the automatic operation of the master cylinder has failed or to stop the initiation of the next step.

When the master is gripped by the master cylinder, the forward ends 207a are disposed below the underside of the master and held in position by the master, so that the roller 209 is prevented from coming into engagement with the minor diameter portion 210a of the cam 210 as contrasted to the position of the roller 209 shown in FIG. 19. This permits the end 208a of the other arm of the bifurcated member 208 to move along a path which is spaced apart from the pin 215, without

10 actuating the switch 217.

While the master gripping operation is being performed as aforementioned, the internally toothed segmental gear 138 is actuated, on the other hand, by the cam 190 having a slightly varying radius of operation.

15 FIG. 22 shows the cam 190, which is fixed with the master cylinder 15, in a position in which it has rotated through substantially 240° counterclockwise from the position shown in FIG. 16, with the roller 191 being maintained in pressing engagement with a minor diameter portion of the cam 190. With the cam 190 in this position, the internally threaded segmental gear 138 is turned counterclockwise about the shaft 140. When the internally threaded segmental gear 138 turns counterclockwise following up the rotation of the cam 190 25 in this direction, the gear 157 which is in meshing engagement with the gear 138, is rotated counterclockwise and the pin 160a, which is secured to the forward end of the arm 160 substantially integral with the gear 157, pivots the support arm 162 in the same direction. 30 This causes the ink repellent etching solution applicator 166 to move from the dash-and-dot position 166A to the dash-and-dot position 166B in FIG. 22, so as to cause the applicator 166 to press against the master. When the support arm 162 moves, the sprocket wheel 35 163 on the shaft 164 rotates in the direction of the arrow in FIG. 23, so that the applicator 166 moves from position 166A to position 166B without applicator 166 rotating about its own axis relative to an immovable part. This brings the underside 166a of the applicator 166, when it is in the position 166A, into engagement with the surface of the master. It is to be understood that the applicator 166 is immersed in a suitable etching solution in the same attitude as it is disposed in the position 166A.

40 45 The shaft 159, which is caused to rotate counterclockwise by the internally toothed segmental gear 138 through the gear 157 and the pin 160a substantially integral with the gear 157, is prevented from rotating in a clockwise direction and returning to its original position by the engagement of the bent portion 167a of the engaging member 167, moving with the shaft 159 as a unit, with the forward end portion of the locking arm 168 as shown in FIG. 22. Thus, the etching solution applicator 166 is prevented from returning to its original position. 50 55 Therefore, as the internally toothed segmental gear 138 turns in a clockwise direction about the shaft 140 while the cam 190 rotates counterclockwise, the gear 157 and arm 160 are returned to their original positions but the etching solution applicator 166 remains in the position 166B.

60 65 The time interval in which the etching solution applicator 166 is maintained in engagement with the master or the etching operation is performed is set beforehand, so that the solenoid 171 is energized upon elapsing of this time to pivot the arm 170 in a clockwise direction about the shaft 169. This causes the pin 174 on the arm 170 to push the rear edge of the locking arm 168 and

cause the arm 168 to swing about the shaft 169, thereby releasing the engaging member 167 from engagement with the locking arm 168. When the shaft 159 is thus released to rotate freely, the etching solution applicator 166 is returned from its operative position 166B to its inoperative position 166A by the action of a restoring spring (not shown).

In FIGS. 11 and 12, when the segmental gear 122 for operating the master feed device is moved about the shaft 124 to the limit of its movement, the square pin 123 is brought into abutment with the projection 410b of the clocking arm 410 from below so as to cause the arm 410 to pivot about the shaft 115, thereby releasing the bent portion 410a (See FIG. 12), engaged in the cutout 116b of the sliding member 116 from engagement therewith. Thus, the first sliding member 116 acts as a unit with the second sliding member 117 which has already been pulled by the spring 131, so that the sliding members 116 and 117 are moved upwardly and obliquely leftwardly by the biasing force of the spring 133 and the arm 119 returns counterclockwise to its original position. This causes the engaging arm 137 (FIG. 14) secured to the arm 118 of the shaft 119 to be restored to its original position where it restrains the movement of the locking piece 139 of the internally toothed segmental gear 138, thereby preventing the actuation of the gear 138. The solenoid 110 is constructed such that it is instantly actuated when a command to feed a master is issued and that it is rendered inoperative immediately after the lever 136 is pivoted.

As aforementioned, the pin 196 of the internally toothed segmental gear 138 moves the free end of the resilient wire 194 upwardly, as shown in FIG. 26, when the gear 138 is moved counterclockwise, causing the locking member 193 to swing in a clockwise direction about the shaft 195. When the internally toothed segmental gear 138 is in the position shown in FIG. 25 before it moves, the roller 186 is maintained in engagement with a major diameter portion of the cam 187 and the arm 183 has moved counterclockwise, with the upright bar 192 being maintained in abutment, at its upper end, with a portion of the oscillating plates 152 or, say, the shaft of the intermediate gear. Thus, the oscillating plates 152 are swung counterclockwise about the shaft 409, thereby maintaining the master supply roller 151 out of engagement with the masters 19. If the roller 186 is brought into engagement with the minor diameter portion of the cam 187 when the locking member 193 is maintained away from the upright bar 192 as shown in FIG. 26, then the arm 183, which is substantially integral with the arm 185, pivots in a clockwise direction, resulting in the upright bar 192 being moved downwardly. This brings the master supply roller 151 into engagement with the master 19. The segmental gear 122 starts rotation immediately after the master supply roller 151 is brought into pressing engagement with the masters 19, so as to feed a master.

Even if the roller 186 is brought into engagement with the minor diameter portion of the cam 187 when the internally toothed segmental gear 138 is engaged by the engaging arm 137 as shown in FIG. 28, the upright bar 192 is prevented from moving downwardly by its bent portion 192a being caught by the hook 193a, so that the master supply roller 151 is maintained in an upper position. It will thus be appreciated that the master supply roller 151 is brought into engagement with

the masters only when the solenoid 110 (See FIG. 11) is actuated.

The locking member 193 is released from engagement with the upright bar 192 when the internally toothed segmental gear 138 moves to a certain degree counterclockwise while the hook 193a and bent portion 192a are maintained in engagement with each other with a strong force as shown in FIG. 28 (the locking piece 139 is maintained out of engagement with the engaging arm 137 at this time) and then the roller 186 is pushed outwardly by the major diameter portion of the cam 187, so that the upright bar 192 moves slightly upwardly to weaken the force with which the bent portion 192a presses against the hook 193a. That is, even if the internally toothed segmental gear 138 rotates, the resilient force of the resilient wire 194 is too small to release the bent portion 192a from engagement with the hook 193a if they are in engagement with each other with a strong force. FIG. 27 shows the engaging member 193 as it is released from engagement with the bent portion 192a by the resilient force of the wire 194 as the roller 186 is pushed outwardly by the major diameter portion of the cam 187 after the internally toothed segmental gear 183 has rotated a certain distance.

The upper roller 176, which functions to feed to the master cylinder the master supplied by the roller 151 (See FIG. 24), is also supported by the oscillating members 178 and 179 and adapted to come into engagement with the lower roller 142 when the arms 182 and 183 have swung in a clockwise direction.

It has already been described that, upon completion of the etching operation, the solenoid 67 (See FIG. 6) is energized so as to perform the operation of applying ink to the master, to which an etching solution has been applied, for a time interval that is set beforehand. When the ink applying operation is completed, a command is issued to feed copy sheets so that a solenoid (not shown) is energized to start the operation of a sheet feed device that has remained inoperative so far.

In FIG. 33, a follower plate 219 is pivotally supported by a shaft 220 secured to the right end surface of the impression cylinder 17 as more clearly shown in FIG. 40. Supported by a shaft fixed to the follower plate 219 is a roller 221 which is adapted to cooperate with a cam 222 fixed to the inner surface of the right side plate 25 of the duplicator. A pin 223 secured to the free end of the follower plate 219 is loosely received in a slot 225 formed in an oscillating plate 224 supported by the outer end of a shaft 226 which is rotatably supported by opposite end plates of the impression cylinder 17 (See FIG. 40). Secured to the shaft 226 are sheet grip pawls 227 which are urged by the biasing force of a spring 228, acting on the oscillating plate 224, to press against a flat surface 403a at the edge of a relatively large cutout 403 formed in the impression cylinder. In FIG. 40, the roller 221 is shown as engaging a major diameter portion of the cam 222 and the follower plate 219 has swung in a clockwise direction about the shaft 220 to cause the oscillating plate 224 to pivot counterclockwise against the biasing force of spring 228, so that the grip pawls 227 are in an open position. A shaft 229, which is rotatably supported by the opposite end plates of the impression cylinder 17 as is the case with the shaft 226, has a follower arm 230 connected to its outer end. A roller 231 supported by a shaft secured to the forward end of follower arm 230 is disposed out-

wardly of the cam 222 so as to cooperate with another cam 232 mounted on the inner surface of the rightside plate 25 (See FIG. 33) of the duplicator. Roller 231 is urged by the biasing force of a spring 233, mounted between the follower arm 230 and a pin on the impression cylinder, to press against the cam 232. Disposed in side by side relation with the shaft 229 to which the follower arm 230 is secured are sheet pushout pawls 234 which are arranged alternately with the sheet grip pawls 227 as shown in FIG. 33. The forward end portion of each push-out pawl 234 is bent toward the inner portion of the impression cylinder, with pawl tips 234a of the pawls 234 being received in recesses 235 formed in flat surface 403a.

In FIG. 34, a thin plate 236, having a bent forward end portion, is mounted on the upper surface of each sheet grip pawl 227, with bent free portion 236a extending inwardly through an opening 237 formed in each sheet grip pawl 227. The bent end portion 236a functions as a stopper against which the forward end edge of a copy sheet, fed and inserted into the open grip pawls 227, strikes.

In FIG. 35, an eccentric shaft 238a is formed integrally with a shaft 238 for supporting the impression cylinder 17 and connected at one end to one end surface of the shaft 238. The eccentric shaft 238a is firmly supported at the other end by a bearing secured to the side plate of the duplicator. A follower plate 239 is fixed to the base of the eccentric shaft 238 and a drive plate 240 is loosely supported at the outer end of the eccentric shaft 238a. A spring 243, of relatively high resilience is connected between a pin 241 on the follower plate 239 and a pin 242 on the drive plate 240, so that the two plates are urged to move toward each other and bent portions 239a and 240a of the plates 239 and 240 respectively abut against each other. The drive plate 240 is normally urged to swing counterclockwise about the eccentric shaft 238a by a spring 244 secured at one end to the side plate of the duplicator. The pivotal movement of the drive plate 240 caused by the biasing force of the spring 244 is limited by the abutting engagement of a roller 245, mounted on the arm of the follower plate 239, with a fixed pin 246.

A hooked lever 247, pivotally supported by a shaft 248 secured to the side plate of the duplicator, is disposed upwardly and rightwardly of the drive plate 240. The hooked lever 247 is provided with a hook 247a which is adapted to engage a bent portion 240b of the upwardly extended arm of the drive plate 240. The hooked lever 247 is normally urged to swing counterclockwise by a relatively weak spring (not shown).

Secured to shaft 248 is an arm 249 having a bent portion 249a which is urged by a spring 250 to press against hooked lever 247. An inner arm 252 having a pin 251 secured to its free end is secured, as shown in FIG. 39, to the inner end of the shaft 248 which is disposed inwardly of the side plate of the duplicator. Accordingly, the arm 249 and inner arm 252 are in fixed relation to each other.

In FIG. 35, disposed rightwardly of the eccentric shaft 238a, there are a hooking member 253 and a short arm 254 pivotally supported by a shaft 255, short arm 254 underlying hooking member 253 inwardly thereof. The hooking member 253 and short arm 254 are connected to each other by a spring 256, and the

short arm 254 and drive plate 240 are connected to each other by a spring 257.

A follower arm 258, having its bent free end engaged by a hook 253a of hooking member 253, is pivotally supported by a shaft 259 which pivotally supports a lever 261 mounting a roller 260 at its upper end. Lever 261 has a lower end which extends to the left side of a roller 262 supported by a shaft secured to the drive plate 240. A light shield plate 263 extending leftwardly from the shaft 259, is substantially integral with the follower plate 258 and has a forward end portion which extends along the inner side of a light receiving opening 264. A lamp (not shown) serving as a light source is disposed outwardly of the light receiving opening. Secured to the light shield plate 263 is the upper end of a connecting rod 265 which is formed at its lower end with a slot 269 which loosely receives therein a pin 268 secured to an arm 267. The connecting rod 265 is urged to move downwardly by a spring 270 secured at its lower end to the side plate of the duplicator. Pin 268 is connected by a spring 272 to a pin 271 on the connecting rod 265, so that arm 267 is urged to follow the connecting rod 265. The arm 267 is secured to a shaft 273 rotatably mounted on the side plate, with an inner arm 274 being secured to the end of the shaft 273 extending inwardly of the side plate. A pin 275 secured to the forward end of the inner arm 274 is received in a cutout 276a formed in the right side edge at the upper end of a connecting arm 276 (See FIGS. 44 and 47). A keep member 277 has an upper end 277a which holds the pin 275 in place in the cutout 276a. Two pins 278 secured to the connecting arm 276 are loosely received in a slot 277c formed in the keep member 277, so that the keep member 277 is slidable with respect to the connecting arm 276. The keep member 277 is urged to move upwardly by a spring 279 secured at its upper end to a pin 278 disposed above the connecting arm.

The connecting arm 276 can be released from engagement with the pin 275 by moving a finger rest 277b of the keep member 277 to open the cutout 276a and then moving the connecting arm 276 about the lower end thereof counterclockwise. The connecting arm 276 is pivotally supported by a shaft 281 connected to the forward end of an arm 280 which is substantially integral with a bifurcated arm 282, arms 280 and 282 being pivotally mounted on a shaft 284 supported at opposite ends by support arms 283 which are secured to the underside of a printed copy receiving tray 285 for receiving printed copies (see FIG. 46).

A pin 286 secured to a bent portion 404a at the end of one arm of a lever 404 is loosely received in the forward end of the bifurcated arm 282. Lever 404 is pivotally mounted on a shaft 405 connected to the underside of the printed copy receiving tray 285 and its other end has secured thereto a pin 287 loosely received in a slot 291 formed in a plate 290 mounted, by a slot 314, on two pins 289 connected to the underside of the printed copy receiving tray 285, for sliding motion back and forth (upwardly and downwardly as seen in FIG. 45). The forward end portion (upper portion as seen in FIG. 45) of the plate 290 is bent upwardly as shown in FIG. 43 to form a wall 290a for striking the rear end edge of the printed copies.

Loosely fitted over a shaft 292, supported at opposite ends by downwardly bent side edges 285a of the printed copy receiving tray 285 to be disposed trans-

versely of the tray substantially in the central portion of its underside, is a tubular shaft 293 having a flange 293a formed integrally therewith to which a link 294, disposed in parallel relation with shaft 292, is fixed at one end. The shaft 294 is pivotally connected, at the other end, to one end of a bell crank 295 which is pivotally connected, at the other end, to the inner end of the plate 290. The bell crank 295 is pivotally supported by a pin 406 connected to the underside of the printed copy receiving tray 285.

A support member 296 having its two legs loosely fitted over the tubular shaft 293 is adapted to move in a slot 297 formed in the printed copy receiving tray and disposed parallel to the shaft 292, its movement being restricted by the major dimension of slot 297. A movable side plate 24 is secured to the upper surface of the support member 296. Disposed below the support member 296 and loosely fitted over the tubular shaft 293 is a cylindrical member 299 in which is threadably engaged a threaded rod 300 having an externally threaded portion at its upper end. The threaded rod 300 extends through the support member 296 to project upwardly of the printed copy receiving tray. A knob 301 threadably engages the externally threaded upper end. If the knob 301 is threadably moved in a direction in which it is removed from the threaded rod 300 (upwardly as seen in FIG. 50), the tubular shaft 293 and cylindrical member 299 can be loosened so that the support member 296 can be freely moved in sliding motion relative to the tubular shaft 293. Thus, it is possible to adjust the position of the movable side plate 24, in accordance with the width of the copy sheets used, by loosening the knob 301 as aforementioned.

On the other hand, a support member 302, forming a pair with support member 296, is loosely fitted over the shaft 292. A cylindrical member 303 is also loosely fitted over the shaft and a side plate 304 is secured to the upper surface of support member 302. Secured to the cylindrical member 303 is a threaded rod 305 which has at its end an externally threaded portion over which a knob 306 is fitted in the same manner as the knob 301 is fitted over the threaded rod 300 associated with the side plate 24. The cylindrical member 303 acts on the shaft 292 in the same manner as the cylindrical member 299 acts on the tubular shaft 293.

In accordance with a command to feed copy sheets, copy sheets 20 are successively fed to the impression cylinder 17. Each sheet fed is inserted at its front end edge between the grip pawls 227 in an open position as shown in FIG. 40 and the flat surface 403a (See FIG. 33) of the impression cylinder 17. Simultaneously as the impression cylinder 17 is rotated counterclockwise and the roller 221 of the follower plate 219 is brought into engagement with a minor diameter portion 222a of the cam 222, the grip pawls 227 are closed to grip the forward end edge of the sheet (See FIG. 41). As the impression cylinder 17 is further rotated counterclockwise in this state and the roller 221 is brought into engagement with a protuberance 222b of the cam 222, the pawls 227 gripping the sheet are opened to release the sheet from gripping engagement by the pawls. At the same time, the roller 231 of the follower arm 230 is released from engagement with a major diameter portion 232a of the cam 232 and brought into engagement with a minor diameter portion 232b thereof, so that the forward end of the released sheet is pushed by

the push-out pawls 234 and removed from the impression cylinder to be discharged into the printed sheet receiving tray.

An inked image on the blanket cylinder 16 is transferred to the sheet gripped by the pawls 227 as the sheet is passed between the blanket cylinder 16 and the impression cylinder.

The roller 231 for actuating the push-out pawls 234 passes by another minor diameter portion 232c before being brought into engagement with minor diameter portion 232b. If the sheet gripped by the pawls 227 is in a proper position, the push-out pawls 234 are checked by the underside of the forward end portion of the sheet, thereby restraining the roller 231 from coming into engagement with the minor diameter portion 232c. However, if the sheet is not properly gripped by the pawls 227 at this time, the movement of push-out pawls 234 is not checked, so that the roller 231 is brought into engagement with the minor diameter portion 232c as shown in FIG. 42. Secured to that end of the shaft 229 opposite to the end to which the follower arm 230 having the roller 231 is secured is an actuating arm 307 which is adapted to move outwardly of the impression cylinder in pivotal motion, as shown in FIG. 42, when the roller 231 is brought into engagement with the minor diameter portion 232c or when the sheet is not properly positioned on the impression cylinder, thereby pushing the pin 251 of the inner arm 252 outwardly. If the pin 251 is pushed outwardly, then the arm 249, which is substantially integral with the inner arm 252 and disposed on the outer side of the side plate of the machine, is swung in a clockwise direction in FIG. 35, so that the hooked lever 247 connected to the arm 249 by the spring 250 is also swung in the same direction.

Slightly before the forward end of the sheet gripped by the pawls 227 is bitten by the blanket cylinder 16 and impression cylinder 17, a protuberance 309a on a cam 309, adapted to rotate with the blanket cylinder 16 as a unit, pushes the roller 260 outwardly and causes the lever 261 to pivot counterclockwise about the shaft 259 as shown in FIG. 36. The lower end of lever 261 causes, the roller 262 to rotate drive plate 240 counterclockwise about the eccentric shaft 238a. The drive plate 240, rotating in this way, is retained in this position as its bent portion 240b at the upper end is caught by the hook 247a of the hooked lever 247 (See FIG. 36). The pivotal movement of the drive shaft 240 in a clockwise direction results in the follower plate 239 being swung in the same direction by the biasing force of the spring 243. As a result, the eccentric shaft, to which the follower plate 239 is secured, rotates simultaneously, causing the shaft 238 to rotate in a clockwise direction to bring the impression cylinder 17 into engagement with the blanket cylinder 16. The sheet passes between the two cylinders in engagement with each other.

If the sheet is not properly gripped by the pawls 227, then the bent portion 240b of the drive plate 240 is not caught by the hook 247a because the hooked lever 247 has already been pulled by the arm 249 and swung in a clockwise direction. That is, the drive plate 240 is moved back and forth in one oscillation by the protuberance 309a on the cam 309 as the pin 251 is pushed outwardly by a forward end edge 307a of the operating arm 307 as shown in FIG. 42.

The force with which the impression cylinder is brought into engagement with the blanket cylinder may be varied depending on the amount of rotation of the shaft 238 with respect to the eccentric shaft 238a. A pressing force adjusting cam 310 is mounted on the side plate of the machine for suitably adjusting the angle of clockwise rotation of the follower arm 239 secured to the shaft 238. The angular position of cam 310 can be adjusted from outside the duplicating machine. By bringing the roller 245 into abutment against the edge of the cam 310, it is possible to adjust the amount of pivotal movement of the follower arm 239 or the degree of force with which the impression cylinder is brought into engagement with the blanket cylinder depending on the type of copy sheets used.

In FIG. 35, as a cam 311, secured to the outer side of the cam 309, is caused to rotate in a clockwise direction with the blanket cylinder 16, a protuberance 311a on the cam 311 slightly pushes a roller 312 of the follower arm 258, thereby loosening the force with which the follower arm 258 is maintained in engagement with the hooking member 253. However, the follower arm 258 is not released from engagement with the hooking member 253 at this time because the latter is pulled by the spring 257, with the follower arm 258 pivoting slightly each time the protuberance 311a on the cam 311 strikes the roller 312. However, if the drive plate 240 moves to a position shown in FIG. 36, its side edge 240c pushes a pin 313 fixed to the short arm 254 to cause the short arm to swing about the shaft 255, so that the spring 256 is charged to urge the hooking member 253 to swing in a clockwise direction about the shaft 255. If the roller 312 is moved downwardly by the protuberance 311a on the cam 311 while the spring 256 is charged, then the hooking member 253 is pulled by the spring 256 to swing in a clockwise direction about the shaft 255, thereby releasing the follower arm 258 from engagement with the hooking member. Then, the follower arm 258 is urged by the biasing force of the spring 270 to swing counterclockwise about the shaft 259 as the protuberance 311a passes by the roller 312. This causes the light shield plate 263 to move downwardly from a position in which it is aligned with the light receiving opening 264, thereby actuating a light receiving element, such as a cadmium sulfide element or a photoelectric tube, disposed behind the opening 264, to produce pulses.

The follower arm 258 is adapted to oscillate only when the drive plate 240 is maintained in engagement with the hooked lever 247 or when the sheet is properly gripped by the pawls 227 on the impression cylinder. While the drive plate 240 is engaged by the hooked lever, the follower arm 258 moves back and forth in one oscillation as the cam 311 makes one complete revolution, and produces a pulse for each oscillation. The number of pulses produced in this way corresponds to the number of copies printed.

As the light shield plate 263 swings, the plate 290, operatively associated with the light shield plate 263 through the connecting rod 265, arms 267 and 274, connecting arm 276, arm 280, bifurcated arm 282 and lever 404, moves in vibratory motion toward slot 314 to jerk the rear edges of printed copy sheets, successively discharged in the direction of arrow in FIG. 44, so as to align properly the forward and rear edges of all the printed copy sheets on the printed copy receiving tray.

On the other hand, the tubular shaft 293 is reciprocated axially through the bell crank 295 and arm 294 in conjunction with the plate 290, so that the movable side plate 24, substantially integral with the tubular shaft 293, moves in vibratory motion to jerk a lateral edge of the printed copy sheets, successively discharged into the printed copy receiving table, so as to align properly the lateral edges of all the printed copy sheets on the tray. A wire 315 shown in FIG. 44 is loosely supported at one end by a shaft 316 connected to a part of the duplicator and received at its free end in a open-topped longitudinal groove 318 formed in a stopper 317 for printed copy sheets. The wire 315 serves to lightly hold down the printed copy sheets on the printed copy receiving table.

When the number of pulses produced has become identical with the predetermined number of copies to be printed, a command is issued by the coincidence circuit to the print end signal generator so that a solenoid (not shown) which remains energized as long as copy sheets are fed to the duplicator may be de-energized. At the same time, the solenoid 26 (See FIG. 4) which maintains the ink applying device operative is also de-energized, so that the ink applying operation is terminated and the pair of ink form rollers 94 and 95 is released from engagement with the master cylinder.

Upon termination of the ink applying operation, a solenoid 319 (See FIG. 51) is energized so that an oscillating plate 340 is moved downwardly by a plunger or armature 341. Energization of the solenoid 319 sets a plate removing device in motion for automatically removing a lithographic plate or master from the master cylinder and ejecting the same into a receiving tray.

Plate 340 is pivotally supported by a shaft 342 fixed to the side wall of the duplicator. Also pivotally supported by the shaft 342, inwardly of the oscillating plate 340, is an engaging arm 343 which is connected to the oscillating plate by a spring 344. The upper side edge of an oscillating arm 346 is urged by the biasing force of a spring 347 to bear against a pin 345 fixed to the elbow portion of the oscillating plate 340. Arm 346 is secured to the outer end of a shaft 348 rotatably supported by the opposite side plates of the duplicator. Peel pawls 349, having sharp forward ends 349a disposed in close proximity to the peripheral surface of the master cylinder 15, are secured at their bases to the shaft 348.

A locking member 407, adapted to cooperate with the engaging arm 343, is secured to the outer end of a shaft 350 rotatably connected to the side wall 1. A contacting member 351 is secured at its upper end to the inner end of the shaft 350. A connecting rod 353, pivotally supported at one end by a pin 352 connected to the oscillating plate 340, is formed at its other end with a slot 354 which loosely receives therein a pin 355 secured to locking member 407. A spring 356 is connected between pin 355 and connecting rod 353.

A master feed roller 357, disposed in close proximity to the peripheral surface of the master cylinder 15, is rotatably supported by the free end of an arm 358 which is loosely supported at its base by a transverse shaft secured to the side plate of the duplicator. Secured to the outer end of arm 358 is a short arm 359 which mounts a pin 360 connected to the locking member 407 by a spring 361. Pin 360 normally presses against a side edge of the locking member.

Upon energization of the solenoid 319 as shown in FIG. 52 after completion of the ink applying operation, the oscillating plate 340 is swung counterclockwise about the shaft 342 against the biasing force of the spring 362 and pulls the locking member 407, connected to the connecting rod 353, by the biasing force of the spring 356, so that the member 407 also swings counterclockwise about the shaft 350. This causes the engaging arm 343 to come into engagement with the locking member 407 as shown in FIG. 55. On the other hand, the short arm 359 is pulled by the biasing force of the spring 361 (See FIG. 52) when the locking member 407 rotates counterclockwise so that the arm 358, fixed with the short arm 359, swings in a clockwise direction, thereby causing the roller 357 to press against the master cylinder 15. At the same time, the contacting member 351 also swings counterclockwise together with the locking member 407, so that its side edge 351a is disposed in the path of movement of the roller 201 (See FIG. 52).

FIG. 52 shows the roller 201 abutting against the side edge 351a of the contacting member 351 after the former has moved counterclockwise with the master cylinder 15, with the result that the opening and closing arm 202 has swung counterclockwise. When the pawls 204 are opened after the anticlockwise movement of the arm 202, the roller 209 is brought into engagement with the minor diameter portion 210a of the fixed cam 210. As the roller 209 comes into engagement with the minor diameter portion 210a, the forward ends of push-out pawls 207 project outwardly, so that the forward end of master 19a clears the master cylinder 15. Further rotation of the master cylinder brings the roller 209 into engagement with the major diameter portion of the cam 210, so that the push-out pawls 207 are withdrawn and the grip pawls 204 are maintained in an open position by the contacting member 351. Further rotation of the master cylinder results in the master 19a being guided by the peel pawls 349, as shown in FIG. 53, and ejected into the master receiving tray 22 (See FIG. 1). Ejection of the master is effected by the master cylinder rotating continuously counterclockwise and the roller 357 pressing against the master cylinder.

If the roller 201 is brought into abutting engagement with the contacting member 351 as shown in FIG. 54, the locking member 407 and a bent portion 343a of the engaging arm 343 are brought into engagement with each other with a strong force. This keeps the oscillating plate 340, pulled by the spring 362, from moving the engaging arm 343 by its pin 345. However, if the roller 201 is released from engagement with the contacting member 351 as shown in FIG. 55, then the locking member 407 is pulled by the spring 356 to move slightly counterclockwise within the limit of the slot 354. This reduces the force with which the locking member 407 is maintained in engagement with the bent portion 343a, thereby releasing the oscillating plate 340 from a locked position. Accordingly, the oscillating plate 340 is restored to its original position by the biasing force of the spring 362 and the master removing device is also restored to its original position shown in FIG. 51. Movable bar or plunger 341 of the solenoid 319 is rendered inoperative before the roller 201 is released from engagement with the contacting member 351.

In FIG. 51, if the solenoid 319 is energized when the roller 201 is disposed in the position shown in a dash-

and-dot line 201A, then the contacting member 351 is prevented by the roller 201 from pivoting and the engaging member 407 is kept from pivoting in a clockwise direction. However, since the springs 356 and 344 are connected between the locking member 407 and connecting rod 353 and between the oscillating plate 340 and engaging arm 343 respectively, the oscillating plate 340 can swing counterclockwise against the biasing force of the springs 356 and 344 when the solenoid 319 is energized as aforementioned. When the roller 201 is released from engagement with the member 351 after the oscillating plate 340 has moved counterclockwise, the master on the master cylinder 15 is ready to be removed therefrom. Then, the master removing operation is performed when the roller 201 is brought into abutting engagement with the contact member 351 as aforementioned.

The duplicator according to this invention is constructed such that washing and cleaning of the blanket cylinder 16 is performed while the master is being removed from the master cylinder. A command to start a blanket cylinder washing operation is issued to a solenoid 363 shown in FIG. 56, which has a movable bar or plunger 364 connected by a spring 367 to an oscillating plate 366 pivotally supported by a shaft 365 secured to the side plate of the duplicator. An engaging arm 368, connected to oscillating plate 366 by a spring 369, is loosely mounted on shaft 365.

A support plate 371, supporting a washing and cleaning roller 370, is supported for pivotal motion about shaft 373 which supports a liquid ductor roller 372, shaft 373 being rotatably supported at opposite ends by the two side plates of the duplicator. Disposed on one end of the shaft 373 supporting the liquid ductor roller 372 is an electromagnetic clutch 374 which is disposed outwardly of the right side plate of the duplicator. A gear 376 formed integrally with a flange 375 is mounted on the shaft 373 for rotation relative thereto. A flange 377 secured to the shaft 373 is disposed between the flange 375 and electromagnetic clutch 374.

Maintained in meshing engagement with the gear 376 is a gear 378 on the outer surface of the right side plate of the duplicator, and gear 378 is secured to one end of a stub shaft mounting, at the other end a gear 379 which is disposed inwardly of the right side plate and maintained in meshing engagement with a gear 381 adapted to be driven by a drive gear 380 secured to one end surface of the blanket cylinder 16. On the other hand, rollers 370 and 372 have gears 382 and 383 fixed to the respective shafts and maintained in meshing engagement with each other.

FIG. 56 shows the solenoid 363 in operative position in which the oscillating plate 366 is pulled by the movable bar 364 to move toward the solenoid 363. A relatively weak spring 384 is connected between the oscillating plate 366 and an immovable part of the machine for returning the oscillating plate 366 to its original position when the solenoid 363 is de-energized. The support plate 371 is normally urged by a spring of relatively high resilient force to swing in a counterclockwise direction about the shaft 373, and an outwardly directed bent portion 371a of the plate 271 371 normally engaged and locked by locking arm 368.

As the oscillating plate 366 is swung in a clockwise direction by the biasing force of the spring 367, the locking arm 368 is urged by the biasing force of the spring 369 to swing about the shaft 365. However, the

locking arm 368 is kept from pivoting because it is engaged and locked by the outwardly directed bent portion 371a of the support arm 371. As a protuberance 385a on a cam 385, secured to one end surface of cylinder 16, pushes a roller 386, mounted on the support plate 371, and causes the support plate 371 to move slightly in a clockwise direction after the solenoid 363 is energized, the force with which the bent portion 371a is maintained in engagement with the locking arm 368 is reduced, so that the locking arm 368 is swung clockwise by the biasing force of the spring 369. Thus, the support plate 371 is released from locking engagement with the locking arm 368 and permitted to swing counterclockwise thereby causing the washing and cleaning roller 370 to press against the peripheral surface of the blanket cylinder 16. The shaft 373 is freely rotatable relative to the gear 376 when the electromagnetic clutch 374 remains inoperative, so that the washing and cleaning roller 370 is caused to rotate counterclockwise in FIG. 56 by the blanket cylinder. This rotation is transmitted to the liquid ductor roller 372 which is immersed in a liquid contained in a liquid fountain 387 and supplies liquid to the roller 370 for removing the inked image on the blanket machine.

The washing and cleaning operation can be performed rapidly and positively if the electromagnetic clutch 374 is actuated. If the electromagnetic clutch 374 is rendered operative, the flanges 375 and 377 are brought into engagement with each other to act as a unit. The gear 376 is driven by the drive gear 380 through the gears 381, 379 and 378, so that the gear 376 is caused to rotate in the direction of its arrow and the rotation of gear 376 is transmitted to the gear 383 and thence to gear 382. This causes the washing and cleaning roller 370 to rotate in the direction of its arrow in FIG. 56 or in the opposite direction from the blanket cylinder 16. Thus, the relative speeds of the blanket cylinder and washing roller at their respective surfaces in contact with each other are increased thereby permitting to perform washing quickly. In order to prevent damage to the contact surfaces of the blanket cylinder and washing roller, which might be caused by frictional dragging, the washing roller is preferably made of felt or other soft material.

The time interval for effecting washing is set before-hand irrespective of whether or not the electromagnetic clutch is used. When the predetermined time has elapsed, the solenoid 363 is de-energized and the locking arm 368 is restored to its original position. The, the protuberance 385a on the cam 385 pushes the roller 386 outwardly, so that the locking arm 368 engages and locks the support plate 371.

As soon as the blanket cylinder washing operation is completed, a command to feed a copy sheet is issued. The sheet feed device becomes inoperative after one copy sheet is fed to the duplicator. This single sheet serves to remove the washing liquid from the peripheral surface of the blanket cylinder and to distinguish between the copies that have already been printed and the copies to be printed in the next following duplicating cycle.

If the duplicator is set to continuous operation before-hand, then the next lithographic plate or master is automatically fed to the duplicator following feeding of the single sheet and the aforementioned cycle of operation is repeated.

In FIG. 1, a printed copy number read-out device 400 is disposed above one end of the master cylinder 15. The edge of a master mounted on the master cylinder 15 is disposed in face to face relation with a light receiving opening provided on the underside of the device 400. A lamp 401 disposed in the lower rear portion of the device 400 serves as a light source for emitting light which illuminates the side edge of a master on which data marks and timing marks are printed. The light emitted by the lamp 401, after illuminating the marks, passes through a lens and reaches a photoelectric transducer element, such as a cadmium sulfide element.

FIG. 29 shows on example of the master. Printed on one side edge of the master are a plurality of sets of digital timing marks each set including figures 0 to 9 and data marks identical in number with the timing marks. Timing marks indicated by T1 represent thousands, timing marks indicated by T2 hundreds, timing marks indicated by T3 tens, and timing marks indicated by T4 ones. Data marks correspond in number to the timing marks 0 to 9. In the example shown, a data mark D1 corresponds to a timing mark 1, a data mark D2 to a timing mark 5, a data mark D3 to a timing mark 2 and a data mark D4 to a timing mark 0. This indicates that the number of copies to be duplicated is 1520. This number is indicated by indication tube 14 provided in the duplicator.

The read-out device, as shown in FIGS. 30 and 31, is provided with a photoelectric transducer element 402d for reading the data marks and a photoelectric transducer element 402t for reading the timing marks. A start mark S is printed on the master in alignment with the data marks longitudinally of the master. As the master rotates together with the master cylinder in a direction A, the photoelectric transducer element 402d first reads the start mark S and then the data marks and timing marks are read by the respective elements. The master cylinder is formed with cutouts for mounting the master thereon. Means must be provided for preventing initiation of read-out upon incidence of light reflected from one of these cutouts on the photoelectric transducer element. Thus, the start mark S is provided so that read-out may not be initiated till the start mark is first read.

In FIG. 32, mark read-out means 500, which is adapted to read the start mark S and data marks D1 to D4 on a master plate, produces an output pulse when the light from the light source 401 is reflected by the start mark S or any one of the data marks D1 to D4 on the master plate and incident on a photoelectric transducer element 402d. Mark read-out means 501, which is adapted to read the timing marks T1 to T4 on the master plate, produces an output pulse when the light from the light source 401 is reflected by any one of the timing marks T1 to T4 on the master plate and incident on a photoelectric transducer element 402t. An output pulse of read-out means 500 is supplied, together with a reset pulse from a flip-flop 502, to an AND circuit 503 whose output is supplied to inverters 504 and 505 whose outputs are differentiated by differentiation circuits 506 and 507 and supplied to inverters 508 and 509 respectively.

An output of inverter 509 is supplied to monostable multivibrators 510 and 511. The time interval during which monostable multivibrator 510 is actuated is set such that it is longer than the pulse duration of an out-

put pulse of mark read-out means 500 produced by the start mark S. The time interval during which monostable multivibrator 511 is actuated is set such that it is shorter than the pulse duration of an output pulse of read-out means 500 produced by the start mark S.

An output pulse of monostable multivibrator 511 is passed through an inverter 512 and supplied, together with outputs of inverter 508 and monostable multivibrator 510, to an AND circuit 513 whose output is produced only when read-out means 500 reads the start mark S and is supplied to a set input terminal S of flip-flop 502 to set it. When flip-flop 502 is set, it ceases to produce reset signals so that AND circuit 503 ceases to produce output signals. A set output of flip-flop 502 is supplied to AND circuits 514 and 515 to permit outputs of mark read-out means 500 and 501 to be taken out through AND circuits 514 and 515.

Thus, an output of mark read-out means 500, produced by any one of the data marks D1 to D4, or a data pulse, is taken out of AND circuit 514, while an output of mark read-out 501, produced by any one of the timing marks T1 to T4, or a timing pulse, is taken out of AND circuit 515. The data pulse and timing pulse are supplied to a memory circuit 516 where the number of copy sheets to be printed (which is 1520 as indicated by the mark on the master plate shown in FIG. 29) is stored.

The memory circuit 516 may consist of shift registers, for example, to which timing pulses are supplied as shift pulses and in which data pulses are stored. Timing pulses are also supplied to a counter 517 where they are counted. The counter 517 produces a carry signal for the position of 1, 10, 100 or 1,000 each time it counts ten timing pulses and supplies it to a matrix circuit 518. The matrix circuit 518 produces an output pulse and supplies the same to a delay circuit 519 when it receives a carry signal for the position of 1 from the counter 517, produces an output pulse and supplies the same to a delay circuit 520 when it receives a carry signal for the position of 10 from the counter 517, produces an output pulse and supplies the same to a delay circuit 521 when it receives a carry signal for the position of 100 from the counter 517, and produces an output pulse and supplies the same to a delay circuit 522 when it receives a carry signal for the position of 1000 from the counter 517.

Outputs of delay circuits 519 to 522 are passed through an OR circuit 523 and a delay circuit 524 and supplied to the memory circuit 516 as reset pulses, and an output pulse of delay circuit 522 is supplied to counter 517 as a reset pulse. Thus, the memory circuit 516 is reset after ten pulses for one column are supplied thereto and produces a carry signal which is supplied to a matrix circuit 525. The matrix circuit 525, which converts carry signal outputs of the memory circuits from decimal notation, to binary notation supplies binary outputs for the positions of 1, 10, 100 and 1,000 to gate circuits 526 to 529 respectively.

Each gate circuit 526 to 529 may comprise AND circuits corresponding in number to bits, for example. Output signals of the delay circuits 519 to 522 are supplied to the gate circuits 526 to 529 respectively for each column so that the bit outputs from the matrix circuit 525 may be supplied to a counter 530. Thus, counter 530 is set to any number of copy sheets to be printed as marked on a master plate (which is 1,520 as shown in FIG. 29). An output of counter 530 is sup-

plied through a matrix circuit 531 to an indication means 532 which indicates in decimal notation the number of copy sheets to be printed.

On the other hand, a pulse generator 533, which is adapted to produce a pulse when one copy sheet is printed, produces a pulse when the light incident on the aforementioned light receiving element from the light source through the light receiving opening 264 is intercepted by the light shield plate 263. Pulses produced by pulse generator 533 are supplied to a counter 534 and counted thereby. Outputs of counters 530 and 534 are supplied to a comparator circuit 535 for comparison and which produces an output signal only when the number counted by counter 530 agrees with the number counted by counter 534 or when the number of copy sheets actually printed reaches the number of copy sheets to be printed as marked on the master plate.

An output signal of the comparator circuit 535, which serves as a printing termination signal, is supplied to a delay circuit 536 whose output signal is supplied to counters 530 and 534 and a reset input terminal of flip-flop 502, so that counters 530 and 534 and flip-flop 502 can be reset after the cleaning solution remaining on the blanket cylinder is wiped and removed by copy sheets.

Counters 530 and 534 and comparator circuit 535 may be of any known form. For example, circuits shown in FIG. 58 may be employed for them. More specifically, counter 530 may comprise sixteen flip-flops 5301 to 5316, bit outputs of gate circuits 526 to 529 are each supplied to a set input terminal of one of these flip-flops and an output of delay circuit 536 is supplied to a reset input terminal of each flip-flop. Set outputs and reset outputs of flip-flops 5301 to 5316 are supplied to matrix circuit 531, and set outputs of the flip-flops are each supplied to one input terminal of a respective AND circuit 53511 to 53514, 53521 to 53524, 53531 to 53534 and 53541 to 53544.

Counter 534 may be in the form of a known circuit in which sixteen flip-flops 5341 to 53416 are continuously connected for counting, in binary notation, the pulses transmitted from the pulse generator 533. Flip-flops 5341 to 53416 are reset by outputs of delay circuit 536 and their set outputs are each supplied to the other input terminal of a respective AND circuit 53511 to 53544. Outputs of AND circuits 53511 to 53544 are supplied to AND circuits 5351 to 5354, one for each column, and outputs of AND circuits 5351 to 5354 are supplied to an AND circuit 5350 whose output signal is taken out as a printing termination signal.

Mark read-out means 500 may be in the form of the circuit shown in FIG. 59, for example. More specifically, opposite ends of a photoelectric transducer element 402d are connected between the junction point between resistors 537 and 538 and a base of an NPN type transistor 539, with the resistors 537 and 538 being connected in series between a positive DC power source and ground. An emitter of transistor 539 is grounded through a resistor 540 while its collector is connected to the positive DC power source through a resistor 541 and to a base of an NPN type transistor 543 through a resistor 542. An emitter of transistor 543 is grounded through a resistor 544 to an output terminal while its collector is connected to the positive DC power source.

Photoelectric transducer element 402d is fired when the light from the light source 401 is reflected by the white background of a master plate and incident thereon. This fires transistor 539 and defires transistor 543 so that the voltage at the output terminal is reduced to zero. However, when the light from the light source 401 is reflected by the start mark or one of the data marks on the master plate and incident on the photoelectric transducer element 402d, the value of resistance of the element is increased and de-fires transistor 539 and fires transistor 543 so that a voltage is produced at the output terminal.

Mark read-out means 501 may be constructed in the same manner as mark read-out means 500. The pulse generator 533 used in mark read-out means 500 may be in the form of the aforementioned light receiving element in place of the photoelectric transducer element.

The electric circuits for operating the solenoids and motor may be constructed as shown in FIG. 60A to FIG. 60C. More specifically, terminals 545 and 546 connected to an AC power source have connected thereto a primary winding L1 of a transformer T through a main switch 547 and a fuse 548 connected in series. A motor M which drives the offset duplicating machine has a common terminal which is connected to one end of the primary winding L1, a low speed terminal which is connected to the other end of the primary winding L1 through a normally closed contact RA1-b1 of a relay RA1, and a high speed terminal which is connected to the other end of the primary winding L1 through a normally open contact RA1-a1 of relay RA1.

A secondary winding L2 of transformer T is connected at opposite ends thereof to an input terminal of a full-wave rectifier circuit 549 whose output terminal is connected to terminals P and N. Thus, when the main switch 547 is closed, the potential of the AC power source is supplied between the low speed terminal and common terminal of motor M to rotate the motor at low speed and actuate predetermined movable parts of the offset duplicating machine to cause them to operate at low speed. The potential of the AC power source is also supplied, through transformer T to full-wave rectifier circuit 549 to be converted into a DC potential which is supplied between terminals P and N. Since solenoid 26 is connected between terminals P and N, it is energized by the DC potential supplied between terminals P and N to enable ink forming to be started.

A normally closed terminal of a switch 550, adapted to be actuated when the start button is depressed, is connected through a resistor 551 to terminal P while a movable contact of switch 550 is connected to terminal N through a capacitor 552. A normally open terminal of switch 550 is connected to the anode of a diode 553 while the cathode of a diode 554 connected to terminal N through a relay RA2 and the solenoid 110 in shunt. The cathode of diode 553 is connected to the cathode of diode 554, and the anode of diode 554 is connected to one fixed terminal 555C of a switch 555 through a normally open contact RA3-a1 of a relay RA3.

When the machine is to be set by the master plate feed switch button 10 to automatically feed one master plate after another to the master cylinder, a movable contact of switch 555, which is connected to terminal P, is manually brought into engagement with one fixed contact 555C. When the machine is to be set such that only one master plate is fed to the master cylinder, the movable contact of switch 555 is brought into engage-

ment with the other fixed contact 555S. A normally open contact RA2-a1 of relay RA2 and a normally closed contact T1M1 b of a timer T1M1 are connected in shunt between the cathode of diode 553 and terminal P, and timer T1M1 is connected between terminals P and N through the normally open contact RA2-a1 of relay RA2.

Thus, when main switch 547 is closed, capacitor 552 is charged through resistor 551 by the DC voltage between terminals P and N. When the start button is depressed, the charge carried by capacitor 552 is discharged through diode 553, relay RA2 and solenoid 110. The discharge actuates relay RA2 which closes its normally open contact RA2-a1 so that the relay is self-held. Relay RA2 is actuated when the magnitude of the discharge current of capacitor 552 is above a predetermined level, and capacitor 552 is charged through resistor 551 when the main switch 547 is closed. Accordingly, relay RA2 is actuated when the start button is depressed after the lapse of a predetermined time interval following the closing of the main switch, which time interval can be set at any level as desired by suitably selecting the values of capacitor 552 and resistor 551.

Closing of the normally open contact RA2-a2 by actuation of relay RA2 permits current to be passed to timer T1M1 which is actuated, after the lapse of a time interval, for which it is set beforehand, following the passing of current thereto, so that its normally closed contact T1M1-b is opened. This interrupts the supply of current to relay RA2 and solenoid 110 which are restored to their original positions. Thus, solenoid 110 is energized for only a short time interval, for which the timer T1M1 is set, so as to mount a master plate on the master cylinder.

A shunt circuit of a relay RA4 and solenoid 171 is connected at one end to terminal N and at the other end to terminal P through a normally open contact RA2-a3 of relay RA2, and through a normally closed terminal of a switch T1M2-S of a timer T1M2 and a normally open contact RA4-a1 of relay RA4. A movable contact of switch T1M2-S is connected to terminal P and a normally open terminal of switch T1M2-S is connected to terminal N through a normally closed contact RA5-b1 of a relay RA5 and a relay RA6 connected in series therewith.

The junction point between normally closed contact RA5-b1 and relay RA6 is connected to a normally closed terminal of a switch T1M3-S of a timer T1M3 through a normally open contact RA6-a1 of relay RA6, and a movable contact of switch T1M3-S is connected to terminal P.

Timer T1M2, which is capable of adjustment of the time intervals to which it is set, is connected between terminals P and N through a normally open contact RA4-a2 of relay RA4. Relay RA5 is connected between terminals P and N through switches 217 and 556 connected in series therewith, and a series circuit of switch 557 and a normally open contact RA5-a1 of relay RA5 is connected in shunt with the series circuit of switches 217 and 556.

Switch 556 is operated by engaging member 167 while switch 557 is actuated as switch 550 is actuated. Relay RA1 is connected between terminals P and N through a normally open contact RA6-a2 of a relay RA6, and a series circuit of the normally open contact RA1-a2 of relay RA1 and a normally closed contact

RA7-b1 of a relay RA7 is connected in shunt with the normally open contact RA6-a2 of relay RA6.

Timer T1M3, which is capable of adjustment of the time intervals to which it is set, is connected between terminals P and N through a normally open contact RA6-a3 of relay RA6. A relay RA8 and solenoid 67 are connected in shunt between terminals P and N through a normally open contact RA6-a4 of relay RA6, and a series circuit of a normally open contact RA8-a1 of relay RA8, a normally closed contact RA3-b1 of a relay RA3 and a normally closed contact RA9-b1 of a relay RA9 is connected in shunt with normally open contact RA6-a4 of relay RA6.

A normally open contact RA10-a1 of a relay RA10 is connected between the junction point between normally open contact RA8-a1 and normally closed contact RA3-b1 and the normally open terminal of switch T1M3-s, and relay RA10 and a solenoid 558 are connected in shunt between the normally open terminal of switch T1M3-S and terminal N.

A relay RA11 and a solenoid 559 are connected in shunt between the junction between normally open contact RA8-a1 and normally closed contact RA3-b1 and terminal N through a normally open contact RA11-a1 of relay RA11, and the junction point between normally open contact RA11-a1 and solenoid 559 is connected to terminal P through a normally open contact RA10-a2 of relay RA10 and a normally open contact RA12-a1 of a relay RA12 in shunt therewith.

Thus, when relay RA2 is actuated and its normally open contact RA2-a3 is closed, current is passed to relay RA4 and solenoid 171 to actuate relay RA4, so that its normally open contact RA4-a1 is closed and relay RA4 is self-held. Solenoid 171 is also energized to permit an ink repellent etching solution to be applied to the master plate on the master cylinder. Actuation of relay RA4 results in its normally open contact RA4-a2 being closed to supply current to timer T1M2 which causes the movable contact of switch T1M2-S to be brought into engagement with the normally open terminal after lapse of a time interval for which the timer T1M2 is set. As a result, relay RA4 and solenoid 171 are restored to their original positions.

Thus, the time interval during which an etching solution is applied to the master plate can be determined by setting timer T1M2. Also, when the master plate is not correctly positioned on the master cylinder, switch 217 is actuated and switch 556 is actuated by engaging member 176 during the time etching solution is being applied, so that a current is passed to relay RA5 to open its normally close contact RA5-b1. As a result, the supply of current to relay RA6 is cut off, thereby preventing the steps which follow to be performed. Switch 557, which is opened when the start button is depressed, is normally closed. It is closed when normally open contact RA5-a1 is closed upon actuation of relay RA5, so that relay RA5 is self-held till the start button is depressed.

When the master plate is correctly mounted on the master cylinder, relay RA5 is not actuated, and when the movable contact of switch T1M2-S is brought into engagement with its normally open terminal, relay RA6 is actuated to close its normally open contact RA6-a1, so that relay RA6 is self-held. When relay RA1 is actuated, its normally open contact RA1-a1 is closed and its normally close contact RA1-b1 is opened. This re-

sults in motor M rotating at high speed and the offset duplicating machine operating at high speed.

When relay RA6 is actuated and its normally open contact RA6-a3 is closed, a current is passed to timer T1M3 which is actuated after the lapse of a time interval for which it is previously set following the supply of current to it, so that the movable contact of switch T1M3-S is brought into contact with its normally open terminal. As a result, relay RA6 is restored to its original position and remains operative during the interval of time for which timer T1M3 is set.

Actuation of relay RA6 actuates relay RA8 and energizes solenoid 67, with relay RA8 closing its normally open contact RA8-a1 and being self-held and solenoid 67 initiating application of ink to the master plate on the master cylinder. Actuation of timer T1M3, after the lapse of the time interval for which it is set, restores relay RA6 to its original position and supplies a current to relay RA10 and solenoid 558, with relay RA10 being actuated and its normally open contact RA10-a1 being closed so that relay RA10 is self-held. Restoration of relay RA6 to its original position restores timer T1M3 to its original position.

Energization of solenoid 558 brings the master cylinder and blanket cylinder into pressing contact with each other. Actuation of relay RA10 and closing of its normally open contact RA10-a2 actuate relay RA11 and energize solenoid 559. Being actuated, relay RA11 closes its normally open contact RA11-a1 so that relay RA11 is self-held. Energization of solenoid 559 initiates supply of copy sheets.

Relay RA7 and solenoid 319 are connected in shunt between terminals P and N through a normally open contact RA9-a1 of relay RA9. A series circuit of a normally closed contact T1M4-b of a timer T1M4 and a normally open contact RA7-a1 of relay RA7 is connected in shunt with normally open contact RA9-a1. Timer T1M4 is connected through a normally open contact RA7-a2 of relay RA7 between terminals P and N. A relay RA13 and solenoid 363 are connected between terminals P and N through a normally open contact RA7-a3 of relay RA7, and normally open contact RA7-a3 and the junction point between relay RA13 and solenoid 363 are connected to a normally closed terminal of a switch T1M5-S of a timer T1M5 through a normally open contact RA13-a1 of relay RA13.

A movable contact of switch T1M5-S is connected to terminal P, and a normally open terminal thereof is connected to terminal N through a relay RA12 and to terminal P through a normally open contact RA12-a2 of relay RA12 and the normally closed contact RA3-b2 of relay RA3 in series therewith. Timer T1M5 is connected between terminals P and N through a normally open contact RA13-a2 of relay RA13.

An output terminal of pulse generator 533 is connected to an input terminal of a monostable multivibrator 560 through a normally open contact RA12-a3 of relay RA12, an output terminal of monostable multivibrator 560 being connected to the base of an NPN type transistor 562 through a resistor 561. A collector and an emitter of transistor 562 are connected to a collector and a base respectively, of an NPN type transistor 563. An emitter of transistor 563 is connected to terminal N and a collector thereof is connected to terminal P through relay RA3.

An automatic setting side terminal of a switch 564, actuated upon depression of button 9 for switching between automatic and manual setting of the number of copy sheets to be printed, is connected to an output terminal of comparator circuit 535. Switch 564 has its movable contact brought into contact with an automatic setting side when the number of copy sheets to be printed is set by means of marks provided on the master plate, and with a manual setting side when the number of copy sheets to be printed is set manually.

A movable contact of the switch 564 is connected to an input terminal of a monostable multivibrator 565, and a manual setting side thereof is connected to a normally open terminal of a switch 566 which is a switch for a known mechanical counter which permits to manually set the number of copy sheets to be printed. When the number of copy sheets for which the machine is set has been actually printed, a movable contact of switch 566 is brought into engagement with the normally open terminal thereof. The movable contact of switch 566 is connected to terminal N through a capacitor 567, and a normally closed terminal of switch 566 is connected to terminal P through a resistor 568.

An output terminal of monostable multivibrator 565 is connected through the resistor 569 to a base of an NPN type transistor 570 whose collector and emitter are connected to a collector and a base, respectively, of an NPN type transistor 571. An emitter of transistor 571 is connected to terminal N and a collector thereof is connected to terminal P through relay RA9.

Timer T1M5 is capable of adjustment of its time intervals. Thus, when the movable contact of switch 564 is connected to the automatic setting side terminal, an output signal of comparator circuit 535 is supplied to monostable multivibrator 565 upon completion of printing of the number of copy sheets automatically set beforehand. When the movable contact of switch 564 is connected to the manual setting side terminal, switch 566 is actuated and the charge carried by capacitor 567 is discharged and supplied to monostable multivibrator 565 upon completion of printing of the number of copy sheets manually set beforehand by means of the mechanical counter. Capacitor 567 is charged through resistor 568 by the DC current between terminals p and N when switch 566 is restored to its original position.

An input is supplied thus to monostable multivibrator 565 upon completion of printing of a predetermined number of copy sheets, so that its output fires transistors 570 and 571 and actuates relay RA9. When relay RA9 is actuated and its normally closed contact RA9-b1 is opened, relays RA8, RA10 and RA11 and solenoids 67, 558 and 559 are restored to their original positions, thereby terminating application of ink and copy sheet feed and releasing the master cylinder and blanket cylinder from pressing engagement with each other. When relay RA9 is actuated and its normally open contact RA9-a1 is closed, a current is passed to relay RA7 and solenoid 319, with relay RA7 being actuated to close its normally open contact RA7-a1 and being self-held. Upon energization of solenoid 319, the master plate mounted on the master cylinder is removed and discharged therefrom. Actuation of relay RA7 also closes its normally open contact RA7-a2 to permit a current to be passed to timer T1M4, which is actuated and opens its normally closed contact T1M4-b upon the lapse of a time interval for which it is set following the

supply of current thereto, so that relay RA7 and solenoid 319 are restored to their original positions.

When relay RA7 is actuated and its normally closed contact RA7-b1 is opened, relay RA1 is restored to its original position so as to reduce the rate of rotation of motor M to a lower level. When relay RA7 is actuated and its normally open contact RA7-a3 is closed, a current is passed to relay RA13 and solenoid 363. Relay RA13 is actuated and its normally open contact RA13-a1 is closed so that relay RA13 is self-held. When a current is passed to solenoid 363 to energize it, cleaning of the blanket cylinder is initiated.

When relay RA13 is actuated and its normally open contact RA13-a2 is closed, a current is passed to timer

15 T1M5 which is actuated, and its switch T1M5-S is actuated after lapse of the time interval for which it is set following the supply of current thereto. This restores relay RA13 and solenoid 363 to their original positions and actuates relay RA12. When actuated, relay RA12 closes its normally open contact RA12-a2 and is self-held. At the same time, its normally open contacts RA12-a1 and RA12-a3 are closed. As a result, relay RA11 is actuated and solenoid 559 is energized, with relay RA11 closing its normally open contact RA11-a1 and being self-held. Energization of solenoid 559 causes a copy sheet to be fed between the blanket and impression cylinders so that the sheet may serve as a marker. An output of pulse generator 533 is supplied to monostable multivibrator 560 upon mounting of the master plate on the master cylinder, and an output of monostable multivibrator 560 fires transistors 562 and 563 to actuate relay RA3. When actuated, relay RA3 opens its normally closed contact RA3-b1 and relay RA11 and solenoid 559 are restored to their original positions.

35 When relay RA3 is actuated and its normally open contact RA3-a1 is closed, relay RA2 is actuated and solenoid 110 is energized in case the movable contact of switch 555 is in engagement with its fixed contact 555C. The aforementioned cycle of operation is repeated again when relay RA2 is actuated and solenoid 110 is energized.

In the present invention, the time intervals for effecting etching, application of ink and blanket cylinder washing are set beforehand after the main switch is turned on. An electric timer or mechanical timer may be used for storing the time intervals that have been set.

50 While the invention has been described with reference to one embodiment of automatic duplication machines of the offset lithographic type, it is to be understood that the invention is not limited to the specific form described, and that many changes and modifications may be made therein without departing from the spirit and scope of the invention which are defined in the appended claims.

55 What is claimed is:

1. An automatic duplicating machine, of the offset lithographic type, using substantially rectangular masters having a leading edge and a trailing edge interconnected by a pair of longitudinal side edges, said machine comprising, in combination, a master cylinder having gripping means operable to grip the leading edge of a master fed thereto; an automatic master feed device operable, responsive to actuation of a start control, to initiate feeding of a master to said master cylinder; the masters fed by said automatic master feed device having impressed thereon markings indicating the respective number of duplicates to be made from each

master; the markings impressed on each master including a first row of timing marks extending longitudinally of one of said side edges thereof and impressed on the master in separated decades with each decade representing a respective column position of a multi-column decimal number, and each timing mark in each of said decades representing a respective decimal digit from 0 to 9; and a second row of longitudinally spaced data marks extending parallel to and spaced laterally from said first row and including one respective single said data mark impressed on the master adjacent each decade of timing marks; each data mark being aligned laterally with that timing mark, of its associated decade, representing the respective decimal digit, in column position, of the decimal number represented by all the data marks and which decimal number represents the number of duplicates to be made from the respective master; a master blanket cylinder engageable with a master on said master cylinder to have impressed, on its peripheral surface, an ink image of the master then mounted on said master cylinder; an impression cylinder adjacent and movable toward said blanket cylinder to press copy sheets against the peripheral surface of said blanket cylinder to provide duplicates of the master; an etching solution applicator operable to apply an ink-repellent etching solution to the master then mounted on said master cylinder; an inking device operable to apply ink to the master; means operable, responsive to completion of the etching solution application, to activate said inking device to initiate application of the ink to the master; means manually operable to preset a preliminary inking time for applying a quantity of ink sufficient to start duplication of the master; a copy sheet feed device; means operable, upon termination of the preliminary inking time, to activate said copy sheet feed device to initiate and continue feeding of copy sheets between said blanket and impression cylinders; a read-out device operable to scan separately the timing marks and the data marks on each master fed to said master cylinder and, responsive to simultaneous scanning, in each column position, of said data mark and its respective laterally aligned timing mark, providing an output signal representing the decimal digit, in the respective column position of the scanned

data mark, whereby to provide decimal output signals indicative of the respective number of duplicates to be made; memory means and a data register connected to said read-out device to receive said output signals and to store and register the indicated number of duplicates; 5 counting means operable to count the number of duplicates produced from each master; signal generating means; coincidence circuit means connected to said memory means; said data register, said counting means and said signal generating means, operable, responsive to coincidence between the stored numbers of duplicates and the counted number of duplicates, to activate said signal generating means to issue a command terminating operation of said copy sheet feed device; master 10 removing means activated, responsive to such command, to remove the master from said master cylinder; and a cleaning device operable automatically, upon completion of duplication of a master, to clean said blanket cylinder.

15 2. An automatic duplicating machine, as claimed in claim 1, in which said markings further include a start mark impressed on each master and aligned with said second row of data marks and positioned between said second row of data marks and said leading edge of the associated master; said read-out device providing indications of the respective number of duplicates to be made only responsive to initial scanning of said start mark.

20 3. An automatic duplicating machine, as claimed in claim 2, in which said read-out device comprises a data mark sensing circuit operable to sense said data marks; a timing mark reading circuit operable to read said timing marks; a temporary data register connected to the outputs of said data mark sensing circuit and said timing mark reading circuit; a carry signal counter connected to the output of said timing mark reading circuit; said first mentioned data register being connected to said temporary data register and to said carry signal counter and registering a count only responsive to signals produced simultaneously by said temporary data register and said carry signal counter; said coincidence circuit means being connected to said first-mentioned data register and to said counting means.
